UNITED STATES PATENT OFFICE

2,142,653

TELEPHONE SYSTEM

Edward S. Peterson, Elmwood Park, Ill., assignor
to Associated Electric Laboratories, Inc., Chicago, Ill., a corporation of Delaware

Application March 16, 1936, Serial No. 69,087

33 Claims. (Cl. 179—26)

This invention relates to telephone systems, but is concerned more particularly with telephone systems wherein automatic switching apparatus in a telephone exchange is remotely controlled by a switchboard operator in a distant exchange, the control being exercised over what is commonly known as an operating trunk.

The broad general object may be stated to be the provision of new and improved circuit arrangements with facilities for enabling the calls originated in a remotely controlled automatic exchange to be handled more expeditiously, as well as to provide a more flexible service than has heretofore been possible with exchanges of this character.

A specific object of the invention is the provision of a novel arrangement whereby two operating trunks may be employed alternatively to handle calls through the same group of automatic switches, whereby simultaneous calls in the remotely controlled exchange may be disposed of more rapidly. The foregoing arrangement depends for its novelty upon the further provision that each of the operating trunks has associated therewith common-control equipment which may be used to supplement any automatic switch with which the operating trunk becomes connected. It is believed that this is the first time two or more common-control equipment units have been provided for the common use of the same group of automatic switches.

GENERAL DESCRIPTION

It has been chosen to illustrate the invention as applied in meeting the requirements of a specific installation wherein the remotely controlled exchange is so located with respect to two attended exchanges that it is convenient to provide the remote control for the setting up of local calls from one attended exchange, while the toll calls to and from the remotely controlled exchange are handled largely through the other.

Of the eighteen figures of accompanying drawings, Fig. 1 is a map showing the remotely controlled exchange and the relative locations of the two nearby exchanges;

Fig. 2 is a trunking diagram showing the interrelation between the groups of equipment in the remotely controlled exchange;

Figs. 3 to 17 are circuit diagrams; and

Fig. 18 shows the way in which the sheets of drawings should be arranged in order that they be understood best.

Referring now particularly to Fig. 1, the three exchanges are shown interconnected by trunk

lines and are designated as Mount Morris, Leicester, and Geneseo, respectively. The Leicester exchange is the remotely controlled exchange; Mount Morris is located relatively near the Leicester exchange, for which reason the remote control over the local switching operations in Leicester is exercised from the Mount Morris exchange; and Geneseo is the exchange from which toll calls originating in or intended for the remotely controlled Leicester exchange are handled, unless such calls are to be directed through the Mount Morris exchange because of the destination or origin of the call.

Two operating trunks are provided between Mount Morris and Leicester designated OT¹ and OT², respectively. The fact that there are only two of these trunks is indicated by the digit 2, located adjacent the operating trunks. Four two-way local-service trunks are provided as is indicated by the local-service trunk LST and the adjacent digit 4. For the handling of toll calls which may be trunked through the Mount Morris exchange from other nearby exchanges (not shown) and intended for the Leicester exchange, the toll line TL¹ is provided. This toll line may also be used for extending calls from Leicester by way of Mount Morris to such other exchanges as may be reached more conveniently through the Mount Morris exchange than through the Geneseo exchange.

The toll line TL² is one of four similar two-way toll lines provided for handling toll traffic between Leicester and Geneseo, as well as between Leicester and any other exchanges reached by way of Geneseo; and the toll line TL³ is one of a suitable number which may be provided between Mount Morris and Geneseo for the purpose of enabling direct toll connections to be made between these exchanges.

The Mount Morris and Leicester exchanges are located sufficiently close together that service is rendered between these exchanges on the same charge basis as service is rendered between subscribers local to either exchange. This is the reason for providing the local-service trunks such as LST for handling this inter-exchange traffic separate from the handling of toll traffic which may be directed from either exchange through the other.

Local layout

50

Referring now particularly to Fig. 2, the arrangement of the equipment in the remotely controlled Leicester exchange will be explained:

The local traffic is handled through finder- 55

connector links, one of which includes the finder F and the interlinked local connector LOC. Each of these switches is denoted by a rectangle having ten short horizontal lines placed beneath it. 5 These short horizontal lines are indicative respectively of the ten levels of bank contacts, as the finder and connector switches are of the usual Strowger, vertical-and-rotary type. The link shown is one of seven similar links as is indicated by the encircled digit 7 placed above the finder F.

The finder F has access to the calling terminals of the local lines by way of line circuits such as LC1 to LC3, while the local connector LOC 10 has access to the called terminals of the lines in common with the toll connectors such as TC1 and TC2.

A feature of the system disclosed is that the same group of connectors serves both four-party 20 full-selective lines and ten-party code-ringing lines. The four-party line FPL is representative of the four-party full-selective lines, and the line TPL is representative of the ten-party code-ringing line. These two lines terminate at the exchange in the line circuits LC1 and LC2, respectively. Service, of course, may be given to single-station lines, preferably by equipping a line with only a single substation with a bridged ringer and using a single one of the ten codes to signal this 30 substation when it is called.

The local-service trunk LST (Figs. 1 and 2) is representative of the four local-service trunks extending between Leicester and Mount Morris. This trunk terminates at the Leicester exchange in the line circuit LC3, which line circuit is similar 35 to the line circuits LC1 and LC2. The local-service calls between Mount Morris and Leicester are therefore handled through the local finder-connector links in Leicester on the same basis as local calls to and from subscriber lines in 40 Leicester.

In order to provide for paystation service, separate paystation lines such as the line PSL of the paystation 1600 are provided. This line extends 45 to the line circuit LC4, which is different from the line circuits LC1 to LC3 in that it is not accessible to the local finders, but is equipped with the line-switch LS which has hunting access to the four local service trunks such as LST. The result is that an originated paystation call is extended over 50 a local-service trunk to the Mount Morris exchange, on the theory that the most paystation calls will be directed to Mount Morris or to some other outside exchange. In the somewhat rare 55 event that a paystation subscriber calls a subscriber of the Leicester exchange, the Mount Morris operator may extend the call back to the Leicester exchange over another of the local-service trunks such as LST. On the other hand, 60 when a paystation subscriber makes a toll call, the Mount Morris operator extends the connection over a toll line such as the toll line TL3, Fig. 1, to the Geneseo toll operator, which operator records the desired call and later calls back over a 65 Leicester-Geneseo toll line such as TL2, Figs. 1 and 2, to recall the paystation when the connection is ready.

In order to control the finders such as F the pre-selecting distributor D, Fig. 2, has hunting 70 access to all of the finders. Start wires extend from the line circuits such as LC1—LC3 to the distributor D so as to cause the distributor to control a pre-selected finder to search for the calling line when a call is originated.

75 The operating trunks OT1 and OT2 terminate

in the common equipment units CE1 and CE2, respectively. Control conductors associated with these two units are multiplied into each of the local connectors such as LOC so as to enable any local connector to become associated with either 5 common equipment unit and the connected operating trunk. The arrangement (to be later described in detail) is such that the operating trunk OT1 is normally taken for use when both are idle, and the operating trunk OT2 is taken for use in 10 the event that a second call arrives while the operating trunk OT1 is in use. By this arrangement, calling subscribers do not need to wait so long in order to secure service when calls are being originated in rapid succession.

15 Each of the toll lines such as TL1 and TL2, Figs. 1 and 2, terminates in a toll connector, such as the toll connector TC1 and TC2, Fig. 2, each toll line passing by way of contacts of a transfer relay in the respective one of the outgoing trunk 20 circuits such as OTC1 and OTC2. These outgoing trunk circuits are interposed between the connector bank terminals assigned to the toll lines for outgoing service and the toll line for the purpose of controlling supervision and signalling 25 operations.

It is customary in connection with a remotely controlled exchange of this general character to provide arrangements whereby a trunk line ordinarily used for other service may be used as an 30 operating trunk during an emergency, such as, for example, following a wind storm or sleet storm which may break down the operating trunk. Since two operating trunks are provided in the system disclosed herein, all of the calls may be 35 handled temporarily over one of the operating trunks in the event that the other becomes temporarily defective. For this purpose, connections are made between the common equipment units and conductors leading from designated contact 40 members of the connector banks so that an operator either in Mount Morris or in Geneseo may dial a pre-assigned number on any connector and cause either of the common equipment units and associated operating trunks to be marked busy, so 45 that no further calls are directed to the defective operating trunk. Subsequently, a different pre-determined number may be dialled so as to unbusy the operating trunk after suitable repairs have 50 been made.

In the event that both operating trunks become 55 defective, the transfer relay 856, Fig. 2, may be caused to operate and transfer the control ordinarily exercised over operating trunk OT1 to the toll line TL2 extending between Leicester and Geneseo, following which calls originating in Leicester may be handled in Geneseo, using the toll line TL2 temporarily as an operating trunk. The reason for placing the operation of the 60 remotely controlled exchange under the control of the Leicester exchange, instead of transferring to an alternative trunk leading to the Mount Morris exchange during the time of the failure of both the operating trunks, is that, in the event of the failure of both operating trunks, there is a strong 65 possibility that the failure is general and that any other pre-assigned trunk line between Leicester and Mount Morris is probably defective. This may occur when a pole has fallen, for example. The transfer relay 856 is caused to operate to 70 make the above-mentioned transfer responsive to the dialling of a predetermined number on any one of the connectors in the Leicester exchange, as is indicated by the disclosed association between this relay and conductors leading from the 75

connector banks. The transfer relay may be subsequently caused to restore responsive to the dialing of a second predetermined number on any of the connectors.

- 5 Provisions are made in the disclosed system for an authorized person to temporarily operate the remotely controlled exchange locally by means of the local control set LCS, as for instance, during an emergency when none of the provided remote 10 operating channels is serviceable.

The circuit drawings

The local arrangement as shown in Fig. 2 having been described, further attention will now 15 be directed to the general aspects of the circuit drawings, Figs. 3 to 17, wherein the circuits of the apparatus of Fig. 2 and the circuits of certain apparatus in the Mount Morris and Geneseo exchanges are shown in detail. As previously mentioned, Figs. 3 to 16 should be arranged as indicated in Fig. 18. The equipment shown in Figs. 3 to 9 and in Figs. 14 to 17 is located in the Leicester exchange; the equipment shown in Figs. 10 and 11 is located in the Mount Morris 20 exchange; and the equipment shown in Figs. 12 and 13 is located in the Geneseo exchange.

Figs. 3, 4, and 5 show the line circuits LC1, LC2, and LC3, respectively, which are associated respectively with the four-party line FPL, the 30 ten-party line TPL, and the local-service trunk LST. These line circuits are similar to each other. Figs. 3, 4, and 5 show also the finder terminals 351, 451, and 551. Through these terminals and multiples thereof, the finders make connection with the calling lines. Figs. 3, 4, and 5 show also the connector terminals 350, 450, and 550. Through these terminals and their multiples, the connectors make connections with the illustrated line when they are called. It is to 40 be noted that the conductors of the local-service trunk LST are reversed at the negative and positive terminals in group 550 and the multiples thereof. This reversal has to do with giving supervision in the Mount Morris exchange, as will be explained hereinafter.

The start conductors 361, 461, and 561 extend to appropriate ones of the level start leads associated with start relay 801, Fig. 8. Each of the start conductors 361, 461, and 561 (as well as 50 each of the other seven start conductors associated with groups of line circuits not illustrated) is multiplied to the ten line circuits reached by way of a given bank level of the finders, in accordance with the usual practice.

Figs. 6 and 7 show the finder F1 and the associated local connector LOC, which are linked together by trunk conductors 624—626. The bank of the finder F1 is not illustrated except for the terminals 351, 451, and 551 connected to the line 60 circuits of Figs. 3, 4, and 5. It will be understood, of course, that there are one hundred such sets of terminals in the bank of the finder F1, and that these terminals are connected in multiple with the corresponding terminals of the other 65 finders.

The bank of the connector LOC, Fig. 7, is not illustrated except for a showing of terminals such as 350, 450, and 550, associated with the line circuits of Figs. 3, 4, and 5. It will be understood, 70 of course, that the bank of the connector LOC is a 400 terminal bank having 100 sets of terminals such as those illustrated in Figs. 3, 4, and 5, which terminals are connected in multiple relationship to the bank terminals of the other connectors in the usual and well known manner.

It is to be noted that the wipers 700 of the local connector LOC are marked —, +, C, and EC, respectively. A similar designation of the terminals of Figs. 3, 4, and 5 is made. From this it is to be noted that no connection is closed by way of the EC wiper of the local connector LOC when a line illustrated in Figs. 3 to 5 is called, as the EC terminal is left unwired at such lines. The EC terminal, it may be mentioned, is used only in the event that a toll line is called, by way of 10 terminals such as 1450, Fig. 14, the EC terminal of which is connected to the circuit by way of the forced-release conductor 1422.

The connector LOC, Fig. 7, is provided with a party selector PS1, used to effect party selection 15 when a party line is called. This party selector has wipers 741 and 742, each of which has a double bank of contacts so disposed as to be bridged in pairs according to the position which the wiper is caused to assume. The wipers are 20 operated in their directive setting by operating magnet 743, and they are restored to the illustrated normal position by the release magnet 744.

Fig. 8 illustrates the distributor D which is composed of a group of relays and the rotary switch mechanism comprising wipers 821—825, driven by the operating magnet 800. Fig. 8 shows also the miscellaneous relay group MG, which includes relays 851—856. The relays in this group are used for miscellaneous purposes which will be 30 hereinafter brought out.

Fig. 9 illustrates the common equipment units CE1 and CE2. The common equipment unit CE1 is illustrated in detail, while of the common-equipment unit CE2 only certain terminals are 35 illustrated, and the conductors which connect thereto. Certain terminals in group 800, appearing at the left-hand edge of Fig. 9, part 1, are not used in the common-equipment unit CE2, and are consequently not shown in group 900 associated with the common equipment CE2. Those terminals peculiar to CE1 have been identified by a line drawn around them, as for example, the five terminals in group 900 associated with the supervisory switch SS. It is preferred, however, for 40 the sake of uniformity in manufacturing procedure that the two common equipment units be made exactly alike. In this way, the common-equipment units are interchangeable, although certain parts of the common equipment CE2 are not needed unless this common equipment should be interchanged with the common equipment CE1.

The operating trunk OT1 is shown extending from the common-equipment unit CE1 of Fig. 9 55 across the top of Fig. 8 to the operating equipment of Fig. 10, located in the Mount Morris exchange. The operating trunk OT2, associated with CE2, is similarly equipped.

Fig. 11 shows the jack and trunk equipment in 60 the Mount Morris exchange associated with the local-service trunk LST. Each of the other three local-service trunks hereinbefore discussed is similarly equipped.

Fig. 12 shows the jack and trunk equipment 65 at the toll board in the Geneseo exchange and associated with the two-way toll line TL2. Fig. 12 shows also the transfer key K3, used to transfer the toll line TL2 from the trunk and jack equipment of Fig. 12 to the control equipment of Fig. 70 13 when the toll line TL2 is to be used temporarily as an operating trunk.

Fig. 13 indicates the control equipment brought into play when the toll line TL2 is used as an operating trunk, which control equipment is 75

similar to that illustrated in Fig. 10 and used in the Mount Morris exchange to exercise the control over the operating trunk OTC.

Fig. 14 shows the outgoing trunk circuit OTC, 5 associated with the toll line TL2, through which outgoing calls to toll line TL2 are made. This outgoing trunk circuit is accessible to the local connectors by way of bank terminals 1450 and multiples thereof, and to the toll connectors by way of terminals 1451 and multiples thereof. 10 This trunk circuit includes the transfer relay 1411 which substitutes the outgoing trunk circuit OTC for the toll connector TC2 when the outgoing trunk circuit OTC is taken for use.

15 The toll connector TC2 of Fig. 13 is used to complete calls incoming to the Leicester exchange from Geneseo. This toll connector, like the local connector of Fig. 7, is provided with a party selector, the party selector of Fig. 15 being designated PS2.

DETAILED DESCRIPTION

The disclosure having been described generally, a detailed description of the operation of the system will now be given.

Local call to a ten-party line

It will first be described how a local call is extended to a ten-party, code-ringing line. For this purpose, it will be assumed that the subscriber at substation 300 on the four-party line FPL desires to converse with the subscriber at substation 400 on the ten-party line TPL. In order to obtain the desired connection, the subscriber at substation 300 removes his receiver 30 and waits for the operator to reply, whereupon he informs the operator of the desired number, following which the operator causes the desired connection to be completed and the desired subscriber to be signalled.

40 When the receiver (not shown) is removed at substation 300, the closure of the usual direct-current bridge across the conductors of the line FPL results in the energization of line relay 301, bridged across the conductors of the line in series 45 with the usual exchange battery and contacts of cut-off relay 301. When line relay 301 energizes, it places a ground potential at its lower armature on the start conductor 361; it disconnects the associated C terminal in group 350 50 from the cut-off relay 302 and connects it to ground, so as to guard the calling line immediately against seizure by way of one of the connectors, and it connects the winding of cut-off relay 302 through contacts of lock-out relay 55 303 to the C terminal in group 351 so as to mark this group of terminals as calling in the bank of finder F1 and the other finders.

It will be assumed that the call is originated 60 at a time when the common equipment units CE1 and CE2 are both idle, and at a time when the wipers 821-825 of the distributor D, Fig. 8, are standing on the terminals of conductors 831-835, extending to the finder F1, Fig. 6. As a result of the idle condition of the common 65 equipment units CE1 and CE2, Fig. 9, a battery potential is maintained on the lower terminal of start relay 801.

Preparing the distributor

70 The placing of the ground potential on start conductor 361 closes a circuit through the corresponding one of the ten-level start leads of Fig. 8 and through the associated isolating resistor for start relay 801. When relay 801 operates it closes 75 a circuit for switching relay 802 from the nor-

mally grounded busy-common conductor 861. Switching relay 802 operates in series with operating magnet 800, but magnet 800 is not operatively energized owing to the relatively high resistance of relay 802. Relay 802 closes a locking circuit for itself at its lower armature, independent of contacts of start relay 801, in addition to starting the finder F1 into operation, as will be pointed out. Switching relay 802 also closes a circuit at its lower armature through 10 contacts of pulse-cut-off relay 808 for hold relay 806 of the relay group including relays 806-808, comprising a restart timer. These three relays cooperate to time the finding operation and to cause a second finder to be taken for use if the 15 first finder fails to find the calling line within a short interval, three seconds, for example. Relay 806 is now operated by its upper winding to open the initial circuit of the now-locked switching relay 802, to prepare locking circuits for the lower 20 windings of relays 804 and 805, and to operate pendulum relay 807 in multiple with its lower winding. Pendulum relay 807 closes an operating circuit for cut-off relay 808 and a holding circuit for the lower winding of relay 806. Cut- 25 off relay 808 now operates and locks itself through the lower contacts of relay 802, breaking the circuit of the upper winding of relay 806 and the circuit of pendulum relay 807. Relay 807 immediately deenergizes and permits its weighted 30 contact member to oscillate. The circuit of the lower winding of relay 806 is broken momentarily on each swing, but the slow-acting relay 808 remains operated until the oscillations have attenuated greatly, at the end of several seconds, 35 for example, which time is sufficient for a normal finder cycle to be completed.

Returning now to the operation of switching relay 802, relay 802 at its inner upper armature prepares a change-over circuit through the upper 40 winding of changeover relay 804 and over control wiper 823; it prepares a circuit for the upper winding of finder-pilot relay 805; it prepares a restart stepping circuit for the operating magnet 800 through contacts of the restart timing 45 relays 806 and 808; it disconnects test wiper 821 from one side of the interrupter contacts associated with operating magnet 800 and connects it directly to the magnet; it extends ground potential at its upper armature through contacts 50 of relays 803, 806, and 804, wiper 824, and vertical conductor 834 to vertical magnet 603 of the finder F1, and it places a ground potential through contacts of finder pilot relay 805 and through wiper 825 on start conductor 835. 55

Starting the finder

Start relay 802 now operates over grounded 60 start conductor 835 and connects the common rotary conductor 836 through contacts of switching relay 601 to rotary magnet 604; it connects the common selecting conductors 961 and 962 with the individual selecting conductors 625 and 626; it removes ground potential at one point 65 from the busy-common conductor 861; it disconnects test conductor 832 from off-normal contacts 607 and prepares an automatic return circuit through overflow contacts 608; and at its upper contacts it applies ground potential to the 70 junction of the two windings of electro-polarized switching relay 601, causing current to flow in the lower or polarizing winding of this relay and preparing a test circuit through the upper winding of the relay by way of the C wiper to enable 75

the finder to test for the calling condition of the marked terminal set.

Vertical magnet 603 operates responsive to the closure of its circuit over conductor 834 upon the 5 operation of switching relay 802 and raises wipers 600 and 609 one step. It also applies ground potential to stepping conductor 832, closing a circuit through wiper 823 for stepping relay 803. Relay 803 thereupon operates and interrupts the 10 circuit of vertical magnet 603, whereupon the vertical magnet 603 restores and opens the circuit of the stepping relay. The stepping relay thereupon restores and again closes the circuit of the vertical magnet. This operation continues until the wipers 600 and 609 have been 15 raised opposite the level of bank contacts containing the calling line.

Finding the calling level

20 When the level of bank contacts containing the calling line is reached, test wiper 609 encounters ground potential over the contact then encountered and through a multiple of the corresponding one of the level start leads indicated 25 in Fig. 8 to the left of the distributor. This encountered ground potential results in an operation (over control conductor 833 and through wiper 823) of changeover relay 804, the operation being brought about by an energization of the 30 upper winding of changeover relay 804 in series with the winding of stepping relay 803, by way of the inner upper contacts of switching relay 802. This operation occurs only after stepping relay 803 has operated and broken the circuit of vertical magnet 603 upon the calling level being reached, and after vertical magnet 603 has restored and removed ground potential from conductor 832 to thereby open the direct stepping 35 circuit of relay 803. It is at this point that the upper winding of changeover relay 804 is energized in series with stepping relay 803. Relay 803 remains operated in series with changeover relay 804 until the changeover relay has operated. Upon operating, relay 804 (whose operation is 40 delayed somewhat by the copper collar on the armature end thereof, as indicated by the solid black upper portion of the relay), locks itself at its inner lower armature through contacts of hold relay 806; it disconnects control wiper 823 from its own upper winding and extends it 45 through contacts of switching relay 802 to the upper winding of finder-pilot relay 805. Relay 805 is not operated at this time, even though the upper terminal of the upper winding thereof is grounded through contacts of switching relay 802, because ground potential is applied to both 50 terminals of the upper winding. At its upper armature, changeover relay 804 transfers the stepping circuit from vertical magnet 603 to the common rotary conductor 836 now extended through contacts of the individual start relay of 55 finder F1, and contacts of switching relay 601, to rotary magnet 604 of the finder. Therefore, when stepping relay 603 now restores responsive to the operation of changeover relay 804, a circuit is closed for rotary magnet 604.

Finding the calling line

Rotary magnet 604 actuates stepping relay 803 70 at its contacts as described in connection with vertical magnet 603. As a result, wiper 609 is brought out of contact with vertical test bank 610, and wipers 600 are stepped across the contacts of the calling level until the terminals 351 75 are reached. The C wiper 600 tests each of the

C terminals with which it comes into contact, but the C terminals of the line circuits encountered by the C wiper of the finder are normally disconnected in the line circuit.

When the line circuit LC1 is reached, however, 5 a call-indicating potential is found by the C wiper 600 of the finder F1 through cut-off relay 302, the upper contacts at the energized line relay 301 and contacts of lockout relay 303. As a result, current now flows from the upper contacts 10 of the energized start relay 602, through the upper or test winding of the electropolarized switching relay 601, in series with the cut-off relay of the line circuit LC1. When it operates, switching relay 601 opens the rotary magnet circuit; 15 opens an additional point in the circuit of release magnet 605; it closes the talking leads 621 and 622; and it connects the C wiper of the finder, the junction of its own winding, and holding conductor 623 together so as to provide a holding 20 circuit for itself and to place ground potential directly on the C lead extending to the line circuit LC1. The holding conductor 623, it may be pointed out, is normally grounded in local connector LOC, Fig. 7, by way of contacts of the 25 forced-release relay 708 and contacts of the cut-off relays 702 and 702'. As a result, switching relay 601 is enabled to remain operated through its lower polarizing and holding winding after 30 start relay 602 has fallen back, as it shortly does.

When the line circuit LC1 is found, and cut-off relay 302 operates in series with switching relay 601 of the finder, relay 302 locks itself directly to the associated finder C lead at its inner upper contacts; at id-s connects line relay 301 and 35 ground potential from the conductors of the calling line FPL; and at its lower armature it closes a circuit for lockout relay 303 so as to operate relay 303 preparatory to locking the line FPL 40 out of service in the event that it becomes defective, which operation will be covered in a subsequent part of the description. With line relay 301 restored and lockout relay 303 operated, ground potential is now removed from start conductor 361, permitting start relay 801 to restore 45 unless another call has been initiated in the meantime. It is to be noted that the restoration of start relay 801 has no immediate affect on the sequential operation of the distributor D, as the switching relay 802 has become locked in the 50 meantime at its inner lower armature as previously pointed out and for the further reason that ground potential has been removed at relays 804 and 806 from the armature of start relay 801.

In the local connector LOC, line relay 706 is 55 now operated over the calling line to operate release relay 707. Relay 707 additionally grounds holding conductor 623.

Delivering the seizing pulse

In the finder F1 switching relay 601 at its lower armature transfers rotary magnet 604 from the 60 rotary operating conductor 836 to control conductor 832, thereby extending a negative potential over control conductor 833, wiper 823, through contacts of the operated changeover relay 804, and contacts of the operated switching relay 802 to the finder-pilot relay 805. Finder-pilot relay 805 now operates and locks itself 65 at its inner lower contacts to ground potential at the lower contacts of the energized hold relay 806. At a separate contact, finder-pilot relay 805 breaks the circuit previously existing over con- 70 75

ductor 835 for start relay 602, while at its inner upper armature it closes a circuit through contacts of seizing-control relay 961 of common equipment CE1 and over conductor 961 (associated with common equipment CE1) to cause the local connector LOC, linked with the finder F1 of Fig. 6, to seize the common equipment CE1. This circuit passes through contacts of the start relay 602. Although the circuit of start relay 602 is broken by relay 805 at the same time that the seizing circuit is closed, the seizing circuit remains closed long enough to permit the seizing operation to take place, as relay 602 is rendered slow acting by the indicated conducting sleeve around its core. It is to be noted that the seizing potential is placed upon the No. 1 seizing or selecting conductor 961 because seizing control relay 961 of the common equipment CE1 is deenergized, indicative of an idle condition of this control equipment, whereas if this relay were in an energized condition and the control common equipment CE2 were idle, then the seizing impulse would be transmitted over the No. 2 seizing or selecting conductor 962, associated with common equipment CE2.

Clearing out the distributor

When the slow-acting start relay 602 restores responsive to the breaking of its circuit by finder pilot relay 805, it disconnects common conductors 836, 961, and 962 from the associated individual conductors, it prepares a circuit for release magnet 605 (which is now maintained open by switching relay 601) through the shifted off normal contact 606; and it places ground potential on test conductor 831, through the shifted off-normal contact 607, to cause finder F1 to test busy to the distributor D and thereby guard the finder from further seizure until it is again freed.

In the distributor D, when ground potential is placed on test conductor 831 a circuit is closed through wiper 821 and contacts of the operated switching relay 802 of the distributor for operating magnet 800. Magnet 800 operates when this circuit is closed, but as is well known the wipers 821—825 do not advance until the magnet restores. The magnet does not restore until switching relay 802 restores responsive to being first short circuited by the closing of the circuit for operating magnet 800 and then disconnected when magnet 800 operates and opens its interrupter contacts.

Upon the restoration of switching relay 802, the grounded test wiper 821 is transferred from its direct connection with operating magnet 800 to its normal connection therewith through the interrupter contacts of the magnet. Magnet 800 thereupon restores and advances the wipers 821—825 one step, at the same time closing its interrupter contacts so as to permit a further automatic hunting advance of the wipers until wiper 821 encounters an ungrounded test contact indicative of an idle finder.

When switching relay 802 is restored, the holding circuit of the lower winding of holding relay 806 is broken. Relay 806 restores after a very slight interval, permitting changeover relay 804 and finder pilot relay 805 to restore when their locking circuit is opened at the inner lower contacts of holding relay 806. Also, cut-off relay 808 is unlocked at the lower contacts of relay 802. With the restoration of these relays, the distributor D has passed through its complete cycle 75 of normal operations and is in readiness to be

started to control the operation of the next selected finder, as ground potential is again extended from the busy-common conductor 861 through contacts of relays 808, 806, and 804 to the armature of start relay 801, so that the start relay may now again control switching relay 802 when the next occasion arises.

The restart timer

It may happen occasionally that a finder becomes defective, either mechanically or electrically, to such an extent that it fails to operate properly to find the calling line. In this event the restart timer composed of relays 806—808 cooperate to cause the distributor D to select another finder and start it into operation in search of the calling line. This operation will now be explained.

It will be recalled that relays 806, 807, and 808 operate successively responsive to the operation of switching relay 802; that relay 808 locks itself energized; and that relay 807 deenergizes and permits its weighted pendulum to vibrate and keep relay 806 operated. While the pendulum of relay 807 is vibrating vigorously, the circuit of the lower winding of relay 806 remains closed almost continuously, and relay 806 remains operated because it is a slow-releasing relay. However, when the vibration of the pendulum attenuates considerably, and assuming that the finder has not found the calling line and permitted the distributor to clear out, relay 806 restores. At its inner lower armature relay 806 removes ground potential from the pendulum contacts, at the same time opening the locking circuit of relays 804 and 805 (assuming that these relays have operated). Also, relay 806 closes a circuit at its middle upper armature from ground at contacts of switching relay 802, through contacts of the operated pulse-cut-off relay 808 for operating magnet 800. The closure of this circuit short circuits relay 802. Magnet 800 now operates preparatory to advancing the wipers 821—825, at the same time disconnecting the short circuited switching relay 802 at its inner upper contacts. Relay 802 now restores and at its lower armature opens the circuit of the locked pulse cut-off relay 808, at the same time opening the circuit of operating magnet 800. Magnet 800 then restores and advances the wipers 821—825 one step. Since switching relay 802 is now restored, wiper 821 is reconnected in the usual hunting circuit with magnet 800, causing this magnet to operate in a buzzer-like manner in search of an idle finder and causing switching relay 802 to remain restored until an idle finder is reached.

Upon the restoration of pulse-cut-off relay 808, ground potential is reconnected to the armature of start relay 801, with the result that switching relay 802 may reoperate as soon as wipers 821—825 have been advanced into association with another idle finder.

It is to be noted that restart timer is effective to re-cycle the distributor D and cause it to advance at any time when switching relay 802 does not become restored in the usual way responsive to the restoration of a start relay (such as 602 of the finder F1) and the consequent application of guarding ground potential to the test conductor (such as 831) within the time allowed for the restart timer to function. In this way, the reliability of the system is greatly improved and the advance of the distributor D following the completion of each connection through a finder is more positively assured.

Overrun of a searching finder

It may happen occasionally that a searching finder fails to find the calling line. This may occur in the event that wiper 609 momentarily makes poor contact with its bank; it may happen in the event that one of the multiple conductors connected in the vertical test bank 610 becomes disconnected; or it may happen because the calling subscriber replaces his receiver after the finder is started and before the finder arrives on the contact of his line. The finder may stop at any one of the levels and rotate entirely over the level, or it may fail to stop at any of the preceding levels and advance to the tenth level. It is to be observed that the contact associated with the tenth level of the finders in the bank 610 is permanently grounded to insure that wiper 609 always finds ground potential when it reaches the uppermost limit of its travel. Then, when the finder rotates over a level and passes off the last contact in its bank, overflow contacts 608 are caused to close. The closing of these contacts, with start relay 602 in an operated position, results in the application of ground potential to test conductor 631, causing the distributor to recycle as heretofore pointed out and advance to the next idle finder. The unsuccessful finder which has been driven to overflow position is restored when it is freed by the distributor.

Seizing the common equipment CE1

The way in which the common equipment unit CE1 is seized will now be explained. When the seizing pulse is delivered, as before explained, to the No. 1 selecting conductor 624 individual to the connector LOC of Fig. 7, selecting relay 701 is operated, to close a locking circuit for itself and to apply an additional ground potential to conductor 625 from the grounded holding conductor 623. At its middle upper armature, relay 701 connects the grounded holding conductor 623 to locking conductor 734 to prepare locking circuits for certain of the relay of the connector; at its upper armature it closes a point in the circuit of the lower winding of back bridge relay 709; and at its lower armature it disconnects connecting relay 703 so as to prevent any possibility of an operation of relay 703 at this time.

As a further result of the grounding of selecting conductor 625, by the initial seizing pulse and at the inner upper contacts of selecting relay 701, a circuit is closed through contacts of cut-off relay 702 and of selecting relay 702' for connecting relay 703. Relay 703 thereupon operates and connects the conductors of cable C1, extending between the common-equipment unit CE1 and the several local connectors, to the local connector LOC, thereby rendering the common-equipment unit CE1 temporarily individual to the local connector LOC.

Responsive to the connecting of rotary conductor 957 of the cable C1 to rotary magnet 717 of the local connector LOC, a circuit is closed through the rotary magnet 717, over rotary conductor 757, and through contacts of relay 923 for start relay 908 of the common equipment CE1. The start relay 908 operates in this circuit, but the rotary magnet 717 does not operate because of the relatively high resistance of the start relay. Start relay 908 places ground potential on conductor 930, thereby closing a circuit through contacts of finder pilot relay 805 (as soon as the finder pilot relay 805 restores in the normal clearing out of the distributor) for seizing-control relay 901. The operation of relay 901 is delayed

until finder-pilot relay 805 restores in order to avoid the premature transfer of seizing ground potential from conductor 961 to seizing conductor 962 of the second-common equipment unit. Relay 901 completes a locking circuit for itself at its inner lower armature to conductor 930, and it removes one battery connection at its lower armature from the lower terminal of start relay 801, so that when both of the common-equipment units are in use, start relay 801 cannot cause needless operation of the distributor.

Start relay 908 also connects up the start and pick-up leads 931 and 032 of the timer T to the answer timer composed of cut-off, alarm, and pick-up relays 909-911. The purpose of this operation is to enable relays 909-911 to operate in conjunction with the timer T to sound an alarm over alarm conductor 949 in the event that the call is not answered within a predetermined maximum time. Further discussion of this operation occurs hereinafter.

Signalling the control operator

As a further result of its previously mentioned operation, start relay 908 closes a circuit at its inner lower armature through contacts of signal-cut-off relay 907 for signal relay 906. Relay 906 thereupon operates signal-cut-off relay 907. Relay 907 operates and locks itself directly to the lower contacts of start relay 908, at the same time disconnecting signal relay 906 and permitting it to restore. During the time that signal relay 906 is operated, the upper trunk conductor of the operating trunk OT1 is opened at the contacts of signal relay 906, which opening it will be understood, is only momentary and is terminated as soon as the relays 906 and 907 have gone through the described operations. This interruption in the continuity of the upper conductor of the operating trunk is for the purpose of signalling the control operator in the Mount Morris exchange.

It is to be noted that the two windings of line relay 913, in series with the windings of the differential supervisory relay 912 and the left-hand windings of repeating coil 941, are bridged across the conductors of the operating trunks OT1 in series with the exchange battery. It will be observed further that the upper winding of line relay 1003, Fig. 10, is bridged across the conductors of the operating trunk OT1 in Mount Morris in series with the associated high-resistance element, by way of contacts of connecting relays 1006 and 1006' and the right-hand windings of repeating coil 1002. Line relay 1003 is normally actuated but the current flow over the line is so limited by the winding of line relay 1003 and the associated resistance element that line relay 913 in the remotely controlled exchange is not normally operated. When the upper conductor of the operating trunk is momentarily interrupted by the described action of signal relay 906 of the common-equipment unit, line relay 1003 momentarily restores and closes a circuit for signal relay 1004. Signal relay 1004 locks itself to ground through the contacts of cut-off relay 1005, so that it remains operated after line relay 1003 has reoperated upon the cessation of the signal interruption produced in the remotely controlled exchange.

At its upper contacts, signal relay 1004 closes a circuit for the call lamp 1007 to attract the attention of the operators at positions 1 and 2 of the Mount Morris switchboard to the fact that a call has been received over the operating

trunk OT1. One of these operators has the headset equipment 1000, and the calling device 1001, while the other operator is provided with headset 1000' and the calling device 1001'. The answer key K1 is a two-way key mounted so as to be within reach of both operators, either of which may manipulate the key to answer the call. When the call is answered by the operator at position 1 the key is thrown to the left, while when the call is answered by the operator at position 2 the key is thrown to the right. The connecting relay 1006 operates in the first instance, and connecting relay 1006' in the second.

The operator answers

Assuming now that the call is answered by the operator at position 1, the operation of connecting relay 1006, responsive to the answering key K1 being actuated to the left, results in the conductors of the operating trunk OT1, as represented by the right-hand terminals of repeating coil 1002, being disconnected from the upper winding of line relay 1003 and the associated high resistance element, and transferred to the impulse contacts of the calling device 1001 at position 1, whereby a low-resistance bridge is placed across the conductors of the operating trunk OT1 to enable the switching apparatus in the remotely controlled exchange to be operated by the calling device. In addition, the conductors of headset 1000 are connected to the extended talking section of the operating trunk OT1, to the left of the repeating coil 1002, and the off-normal contacts of the calling device 1001 are connected to the talking conductors. The operator's equipment is thus placed in talking and dialling relationship to the operating trunk OT1.

The operator may now converse with the calling subscriber at substation 300, the connection being over the operating trunk by way of the windings of repeating coil 947, and through cable conductors 951 and 952 and contacts of connecting relay 703, to the talking conductors 621 and 622 in the finder-connector link.

Preparing the dialling circuit

When the impulse contacts of the calling device 1001 in the Mount Morris exchange are connected across the conductors of the operating trunk OT1, line relay 913 in the common-equipment unit CE1 operates over the operating trunk, but the differential, supervisory-release relay does not operate. Line relay 913 closes a circuit for release relay 914. Relay 914 connects the common, dial or impulse conductor 934 to the back contact of the armature of line relay 913, preparatory to the transmission of impulses to the connected local connector. Relay 914 also operates the release auxiliary relay 915, which in turn operates the release auxiliary relay 916. Release auxiliary relays 915 and 916 prepare various circuits to be subsequently described, and relay 916 places ground potential on the associated locking conductor 935 to prepare locking circuits for certain of the associated relays.

Since a substation on a ten-party line is being called, the called number consists of tens and units digits indicative of the line desired, and one or two party digits indicative of the station or party desired.

Dialling the tens digit

When the dial (not shown) of the calling device 1001 is turned in accordance with the desired

tens digit, the off-normal contacts thereof come into engagement to shunt the talking conductors of the operator's headset, and they remain in engagement until the calling device again reaches its normal position. The impulse springs in the calling device are separated momentarily the desired number of times to thereby send the desired number of impulses. This operation is repeated for each of the subsequently dialled digits.

In the remotely controlled exchange, line relay 913 restores momentarily each time the circuit is opened at the impulse contacts of the calling device, but the slow-acting release relay 914 remains operated. Upon each of its momentary restorations line relay 913 delivers an impulse through contacts of release relay 914 over the common impulse conductor 934. During the tens digit, each of these impulses passes from conductor 934 through contacts of relay 923 to the vertical magnet impulsion conductor 956. From this conductor, the impulses pass through contacts of the operated connecting relay 703 of the connector to vertical magnet 716. By the operation of vertical magnet 716, the wipers 700 of the connector are raised step by step until they come to rest opposite the desired level of bank contacts. When the wipers of the connector are raised from their normal position, the off-normal contacts associated with guard conductor 624 (interconnecting the finder F1 with the connector LOC) make an additional ground connection to conductor 624 to insure that the finder-connector link is maintained guarded against seizure by the distributor of Fig. 8. Off-normal contacts 719 prepare a circuit for release magnet 718, and off-normal contacts 720 place a ground potential on the generator-start lead 725 so as to start the exchange generator into operation preparatory to signalling over the desired line.

In the common equipment CE1 of Fig. 9, the impulse series relay 918 is a slow-acting relay permanently connected between the common impulse conductor 934 and the negative pole of the exchange battery. In addition, the upper winding of series-auxiliary relay 919 is connected parallel with the winding of relay 918. As a result, both of these relays energize when the first impulse of a series is delivered over conductor 934. Relay 918 closes a holding circuit for the lower winding of relay 919 so as to maintain the series-auxiliary relay 919 operated until relay 918 restores at the end of the series of impulses. It is to be noted that relays 922 and 923 constitute a pair of counting relays arranged to become completely actuated at the end of the tens digit. Series-auxiliary relay 919, upon operating at the beginning of the tens digit, closes a circuit through contacts of relay 923 for relay 922. Relay 922 operates and closes a locking circuit for itself at its lower contacts to the grounded conductor 935 through the winding of relay 923. Relay 923, however, does not operate for the time being because it is short circuited by the initial circuit for relay 922. However, when series relay 918 restores at the end of the tens digit and permits relay 919 to restore, the initial circuit of relay 922 is opened, but relay 922 remains operated in the locking circuit through relay 923, and relay 923 operates. Upon operating, relay 923 disconnects the control contacts of relay 919 from the junction of its own winding and that of relay 922 and prepares to extend them through to the next pair of counting relays (925 and 926). Relay 923

also disconnects the common impulse conductor 934 from vertical conductor 956 and transfers it to rotary conductor 957 by way of contacts of the units-digit relay 924. In order to maintain start relay 908 operated, relay 923 transfers the actuating conductor associated with this relay from rotary conductor 957 to the vertical conductor 956, as the vertical conductor 956 has now been used for impulsive and rotary conductor 957 will be the next to receive impulses, which would probably cause the start relay 908 to restore by their short circuiting action. Since no further impulsive will occur in this call over vertical conductor 956, start relay 908 may remain connected to vertical conductor 956 until the call is completely put through, and still remain under the control of connecting relay 708.

Dialling the units digit

When the units digit is dialled, each resulting momentary restoration of line relay 913 results in the closure of a circuit over the common impulse conductor 934 and through contacts of the now-operated counting relay 923 to rotary conductor 957, by way of contacts of units digit relay 924. These impulses are further delivered over conductor 957 and through contacts of connecting relay 703 to rotary magnet 717. Rotary magnet 717 rotates the wipers 700 of the connector into engagement with the terminals of the called line, in this case terminals 450, Fig. 4, or multiples thereof, as the ten-party line TPL is the called line.

Series and series-auxiliary relays 918 and 919, are again energized throughout the series of impulses. In order to test the called line as to its busy or idle condition, series auxiliary relay 919 disconnects test conductor 960 from the lower winding of idle-test relay 921 and connects it to the lower winding of busy-test relay 917. As a result, busy relay 917 operates each time the test wiper (the C wiper) in wiper group 700 of the connector LOC passes over a grounded test contact. In the event that the called line is busy, busy test relay 917 is in an energized condition when the wipers come to rest on the terminals 450, because the C terminal of this group is grounded when the line is busy. Under this condition, idle-test relay 921 cannot operate, and the connection is denied, as is pointed out more in detail hereinafter.

The called line is idle

Assuming that the desired line is idle when called, busy-test relay 917 is not in an energized condition when the wipers 700 of the connector come to rest on the terminals 450. Under this condition, idle-test relay 921 is operated in a circuit which passes through the lower winding of relay 921, from the grounded locking conductor 935, and thence by way of contacts of relays 919 and 921 to the common test conductor 960. The circuit extends thence through contacts of connecting relay 703, contacts of busy relay 704, through the C wiper 700 and the C terminal 450 to the ungrounded pole of the exchange battery, by way of the cut-off relay (not shown) in the line circuit LC2. The cut-off relay of the called line is energized in this circuit in series with the idle-test relay in the common equipment, and it clears the called line for ringing and conversation.

In the common equipment CE1, idle test relay 921 closes a locking circuit for its upper winding to the grounded conductor 935, and at its inner lower armature it transfers the common test lead

960 from the test circuit to the grounded conductor 935 thereby insuring the maintenance of ground potential on conductor 960 during the dialling of the party-selecting portion of the number and providing a more direct ground potential than previously existed by way of the lower winding of relay 921. At its upper armature, relay 921 disconnects the forced-release conductor 954 and connects up the cut-off conductor 955 for a purpose which will be later apparent. The upper winding of units-digit relay 924 is energized in parallel with the upper winding of idle-test relay 921 to transfer the impulse conductor 934 from rotary conductor 957 to the party-selector operating conductor 958.

15

The code selecting arrangement

At this point it is convenient to describe the code selecting arrangement more fully in order that the special provisions of the system may be better appreciated. In a system wherein ten-party service is provided the usual arrangement is to provide a party selector such as the party selector PS1 of Fig. 7, part 2, responsive to a single party digit which may give the code selector any one of ten desired settings. It is to be observed that the party selector PS1 has ten off-normal positions, corresponding to the ten illustrated sets of contacts. The last four contact sets in the bank of wipers 741 and 742, however, are used to provide four-party, full-selective service, leaving only six contact sets available for controlling the ten-party selection. This difficulty has been surmounted by the use of contact sets 2 to 6 of wiper 741 which are used to apply codes for signalling the first five parties on the line, and contact sets 2 to 6 in the bank of wiper 742 to apply the ringing code for the signalling of the remaining five parties. When any one of the first five stations on a ten party line is to be signalled, one of the party digits 2 to 6 used to select any one of the first five coded generator leads 746, but when one of the remaining five stations on the line is to be signalled it is necessary to cause a switching operation to occur to substitute wiper 742 for wiper 741. This is accomplished by dialling the digit 1 as a preliminary party digit for the selection of any one of the last five stations on the line, following which a party digit ranging in value from 1 to 5 is dialled which further advances the wipers of the party selector to cause wiper 741 to contact any desired one of its contact sets 2 to 6 and thereby connect up any one of the coded generator leads 747.

For the purpose of illustrating the operation to the best advantage, it will be assumed that the tenth station on the line is the one desired, the party selecting portion of whose number is composed of digits 1 and 5, which follow the tens and units digits having to do with line selection. That being the case, the operator dials the party digits 1 and 5 following the dialling of the tens and units digits.

Dialling the party digit 1

Returning now to the detailed description of the operation, when the operator dials the party digit 1, following the dialling of the units digit, one impulse is delivered by line relay 913 over the common impulse conductor 934. This impulse is transmitted by way of contacts of the actuated tens-digit relay 923 through contacts of the actuated units-digit relay 924 and through contacts of relays 926 and 928 to the party-selector operating lead 958. This impulse passes

75

through contacts of relay 703 to the operating magnet 743 of the party selector PS1. By the operation of magnet 743, wipers 741 and 742 are advanced one step in order to cause circuit operations to take place which will prepare for the dialling of a further party digit.

When wiper 742 stops on its first set of contacts and thereby bridges them, a series circuit is prepared for code-group relay 713 and code-group-pilot relay 920 (of the common equipment CE1) over pilot conductor 959, but this circuit remains open until series relay 918 falls back at the end of the digit, in order to avoid operating relays 713 and 920 when a digit of higher value 15 is dialled as the first party digit.

When relay 918 restores, the upper winding of code-group-pilot relay 920 is energized in series with code-group relay 713. Code-group-pilot relay 920 operates immediately in this circuit, but 20 the operation of code-group relay 713 is delayed somewhat by the slow-acting characteristic of the latter relay. Upon operating, code-group-pilot relay 920 closes a locking circuit for itself, at its inner lower conductors to the grounded conductor 935 shunts the upper contacts of the first-party-digit counting relay 926 so as to prevent relay 926 from opening the impulse circuit over conductor 958 to the operating magnet 743 of the party selector, as it would otherwise do.

With tens-digits and units-digits relays 923 and 924 operated, the last-mentioned operation of series auxiliary relay 919 results in the operation and locking of relay 925 upon the start of the first party digit, and the restoration of the series auxiliary relay 919 at the end of the first party digits results in the operation of relay 926 in the locking circuit of relay 925.

In the connector LOC, code-group relay 713 operates slightly the corresponding pilot relay 920 and closes a locking circuit for itself to the grounded conductor 734. Relay 713 also transfers the ringing digit from contacts 2 to 6 of wiper 741 to contacts 2 to 6 of wiper 742, preparatory to signalling one of the second five stations on the called party line, instead of one of the first five stations.

Dialling the second party digit

When the second party digit (assumed to be 50 the digit 5) is dialled, the five resulting impulses are transmitted by line relay 913 over common impulse conductor 934 to the party-selector operating conductor 958. These impulses pass through contacts of the operated relays 923, 924, and 55 920 and through contacts of the unoperated relay 929. Operating magnet 743 thereby receives five additional impulses, whereupon it advances wipers 741 and 742 from the first-position contacts into engagement with the sixth-position 60 contacts.

When series auxiliary relay 918 operates at the beginning of the second party digit it closes a circuit through contacts of the operated relays 921, 924, and 925, and through contacts of relay 65 928 for relay 927 of the second party-digit counting relays 927 and 928. Relay 927 operates and closes a locking circuit for itself in series with relay 928, with the result that relay 928 operates in series with relay 927 when the initial circuit 70 of relay 927 is opened upon the restoration of series auxiliary relay 919 at the end of the second party digit. Relay 928 finally opens the counting-relay operating circuit at its inner upper contacts, while at its upper contacts it opens the operating circuit over conductor 958.

Clearing out the common equipment

Having dialled the desired number, the control operator in Mount Morris restores the key K1, Fig. 10, permitting connecting relay 1006 to restore and disassociate equipment 1000 and 1001 from the operating trunk OT1. Relay 1006 also again bridges the upper winding of line relay 1003 across the upper conductors of the operating trunk, and this relay reoperates over the trunk 10 in series with the distant line relay and disconnects signalling relay 1004 before the cut-off relay 1005 can restore and operate relay 1004 through the contacts of relay 1003. The restoration of relay 1005 is delayed momentarily by the 15 circulating current passing through the winding of the relay and through the shunt resistor to give the line relay 1003 time to disconnect relay 1004.

In the remotely controlled exchange, line relay 913 in the common equipment unit CE1 restores 20 and remains restored when the connecting relay 1006 falls back, as the current which flows through the upper winding of relay 1003 and the associated resistor is insufficient to maintain line relay 913 in operated position.

Relay 913 delivers an impulse over the common impulse conductor 914 to the series relay 918 and the series auxiliary relay 919, but this impulse is not permitted to reach the local connector because the relay 918 has opened the 30 impulsive circuit at its upper contacts. Release and auxiliary release relays 914, 915, and 916 now restore at short successive intervals, as each of them is a slow-releasing relay. Relay 914 opens the impulse being delivered to conductor 934, permitting relays 918 and 919 to restore. Ground potential is maintained on locking conductor 935 until relay 916 restores. Upon the restoration of relay 915, a circuit is closed 40 through contacts thereof and through contacts of the still-operated relay 916, through contacts of the non-operated busy-test relay 917, contacts of the operated idle-test relay 921, over common cut-off conductor 955, and through contacts of connecting relay 703, for the winding of cut-off relay 702. Relay 702 operates and locks itself in multiple with the winding of selecting relay 701, through the inner upper contacts of relay 701 to the grounded holding conductor 623. Connecting relay 703 is disconnected by the normally closed contacts controlled by the inner lower armature of cut-off relay 703, and therefore restores, disassociating the local connector LOC from the common equipment unit CE1.

In the common equipment CE1, start relay 908, 55 which has been maintained operated over conductor 956 since the operation of relay 923 at the end of the tens digit, restores upon the restoration of connecting relay 703. Relay 908 thereupon opens the locking circuit of signal-cut-off relay 907 and the locking circuit of cut-off relay 909, permitting these relays to restore also.

The final slow-acting relay 916 restores shortly and removes ground potential from conductor 935, permitting the locked relays of Fig. 9, part 65 2, to restore. With relays 916 and 908 restored, ground potential is now removed from conductor 930 to permit the locked seizing-control relay 901 to restore, unless a further call has arrived in the meantime and the operation responsive 70 thereto has proceeded to the point where finder pilot relay 805 has become operated, in which case common equipment CE2 has become selected and finder-pilot relay 805 maintains conductor 930 grounded to maintain seizing-control 75

relay 901 operated through the inner lower contacts thereof until the distributor D has gone through its cycle of operations. In any event, relay 901 restores when conductor 930 finally becomes ungrounded, and upon doing so it again prepares to transmit the next seizing impulse over conductor 961 associated with common equipment CE1 instead of over conductor 952 associated with common equipment CE2.

10 *Signalling the desired substation*

When cut-off relay 702 is operated as above described it connects pick-up conductor 735 through contacts of busy relay 704 and O-level shaft contacts 724 to pick-up relay 711. At the same time, relay 702 places ground potential on the interrupter-start conductor 736 by way of contacts of busy relay 704 and contacts of ring cut-off relay 710, in order to start the ringing interrupter and code-generating apparatus into operation, the ringing generator itself having been started by way of generator-start conductor 725 upon the operation of off-normal contacts 720.

25 As soon as the pick-up lead 736 becomes grounded, pick-up relay 711, which serves as a combined pick-up relay and switching relay (wiper-connecting relay) operates over the pick-up lead and closes a locking circuit for itself to the grounded holding conductor 734, at the same time opening the pick-up circuit. Relay 711 connects up the negative and positive wipers in group 700 to prepare the ringing and talking circuits, and it also completes the ringing circuit at its inner upper contacts through contacts of the operated code-group relay 713 and the sixth position contacts of wiper 742. As a result a coded application of ringing current (consisting of one long ring followed by five short rings) is received over the fifth of the code-generator leads 747. This ringing current passes through the sixth position contacts of the bridging wiper 742, through contacts of the operated relays 713 and 711, through the upper winding of ring-cut-off relay 710, through contacts of the positive-biased-generator relay 714, contacts of the line-reversing relay 715, upper contacts of ring-cut-off and pick-up relays 710 and 711, and by way of the negative wiper 700 and the corresponding terminal in group 450 to the negative conductor of the ten-party line TPL. This ringing current passes through the ringer at the bridged substation 400, and through each of the other nine ringers on the line (assuming that the line TPL is fully equipped), and returns to ground over the positive conductor of the line and positive terminal in group 450, positive wiper 700, contacts of pick-up and ring-cut-off relays 711 and 710, to ground by way of the upper contacts of line-reversing relay 715. The ringing current is presumed to be superimposed on the negative pole of the exchange battery, as is common practice.

Completing the talking circuit

65 When the called subscriber at substation 400 responds to the ringing of his bell in accordance with the code assigned to his station, by removing his receiver, the closure of the usual direct-current bridge across the conductors of his line permits ring-cut-off relay 710 to operate, which relay does not operate ordinarily because it is designed not to operate in series with the condensers included in circuit with the substation ringers. At its inner lower contacts, ring-cut-off relay 710 closes a locking circuit for its lower

winding to the grounded locking conductor 734. Ring-cut-off relay 710 also opens the ringing circuit and completes the talking circuit at its upper and inner-upper armatures. In addition, relay 710 removes ground potential from the interrupter-start lead 736 in order to avoid needless operation of the ringing interrupter.

5 Back bridge impedance 709 now supplies talking current to the called substation by way of contacts of the operated selecting relay 701.

10 The calling and called subscribers may now converse with each other as desired.

While the ringing current is being applied to the called line, the calling subscriber is kept informed of the ringing operations by virtue of the 15 connection of the small-capacity condensers 731 and 732 between the ringing circuit and the incoming talking conductors 621 and 622.

20 *Clearing out the established connection*

When the conversation has been completed and the subscribers have replaced their receivers, the consequent opening of the circuit of line relay 706 of the local connector results in the deenergization of line relay 706 and the consequent restoration of release relay 707. With 25 cut-off relay 702 operated and locked to holding conductor 623, the restoration of release relay 707 results in the removal of ground potential from holding conductor 623. This opens the 30 locking circuit of cut-off relay 702, and cut-off relay 702 restores and reapplies ground potential to hold conductor 623, but the reapplication of ground potential to this conductor is delayed somewhat by the slow-releasing characteristics 35 of relay 702. Selecting relay 701, ring-cut-off relay 710, pick-up relay 711, and code-group relay 713 restore pursuant to the clearing out of the connector. In addition, in the interval 40 ground potential is removed from holding conductor 623, switching relay 601 of the finder F1 restores, as does the cut-off relay 302 of the line circuit LC1.

The cut-off relay in the line circuit LC2, corresponding to cut-off relay 302 in the line circuit LC1, is permitted to restore and the guarding 45 potential is removed from the C conductor of the called line when the C wiper 700 of the local conductor LOC becomes ungrounded upon the restoration of cut-off relay 702.

The local connector is restored to normal position when release magnet 718 operates through off-normal contacts 719 upon the restoration of selecting relay 701. The release-magnet circuit is opened at off-normal contacts 719 when the connector returns to its normal position. The 55 party selector PSI is cleared out by the operation of release magnet 744 through off-normal contacts 725.

In the finder F1, the wipers 600 are disconnected upon the restoration of switching relay 601. In addition, a circuit is closed through contacts of relay 601, the shifted off-normal contacts 606, and contacts of start relay 602 for release magnet 605. Magnet 605 thereupon operates to effect the restoration of the finder F1 to normal position, whereupon the release-magnet circuit is opened at off-normal springs 606.

With the local connector LOC in normal position, ground potential is removed at one point 70 from guard conductor 624 by off-normal contacts of the connector, and ground potential is additionally and finally removed from guard conductor 624 when off-normal spring 607 of the finder F1 is returned to the normal position illus- 75

trated in the drawings. Ground potential is thereby removed from test conductor 831.

Calling busy lines

In order to explain the operations that occur when a line is called at a time when it is already in use, it will now be assumed that the ten-party line TPL, Fig. 4, is busy when the subscriber at substation 300 on the line FPL attempts to call the subscriber at substation 400 on the line TPL as hereinbefore described. In this event, the operations proceed as hereinbefore described until the units digit is dialled by the operator and the resulting impulses received by the rotary magnet 717 of the local connector cause the wipers 700 to be rotated into engagement with the terminals 450 associated with the busy line TPL. At this time, the ground potential existing on the C terminal of group 450 and the multiples thereof, because of the busy condition of the line, is encountered by the C wiper 700 of the local connector and is thereby extended by way of contacts of busy relay 704, contacts of the actuated connecting relay 703, and test lead 960, to the common equipment CE1. From test lead 960, this ground potential extends through contacts of the idle-test relay 921 to the inner lower armature of series-auxiliary relay 919. It will be recalled that series relay 918 and series auxiliary relay 919 are maintained operated throughout each series of impulses. As a result the encountered ground potential is further extended through the inner lower armature of series auxiliary relay 919 to the lower winding of busy test relay 917. Busy test relay 917 is therefore operated to prepare a locking circuit for itself at its lower armature and to open a point in the test circuit of the lower winding of idle-test relay 921. This locking circuit for the lower winding of busy-test relay 917 is completed to the grounded conductor 935, through the normally closed contacts controlled by the inner lower armature of relay 919, when the said relay 919 restores at the end of the units digit. Busy test relay 917 also prepares a special locking circuit for its upper winding; it prepares to transmit an impulse over cut-off lead 955; it prepares to transmit an impulse over busy lead 953; and at its upper armature it makes a connection from the common busy-tone lead 936 through the associated current-limiting condenser to the lower conductor of the operating trunk, thereby causing a busy tone to be heard by the calling operator and to be induced through the windings of the repeating coil 947 so that it is heard by the calling subscriber. In addition, the lower winding of units-digit relay 924 is operated in multiple with the now-energized lower winding of busy-test relay 917, through the lower contacts of the restored series auxiliary relay 919 to disconnect rotary conductor 957 so as to prevent a further advance of the wipers 700 when the operator clears out the common equipment unit. At its lower contacts relay 924 locks itself to the winding of busy relay 917 by shunting the lower contacts of relay 919.

When the operator restores her key as hereinbefore pointed out to clear out the common equipment unit, the release of relays 913 to 916 and the consequent unlocking and restoration of the remaining relays of the common equipment unit EC1 takes place substantially as hereinbefore described. When relay 913 restores it closes a prepared locking circuit for the upper winding of busy-test re-

lay 917 through contacts of release auxiliary relay 916 to maintain relay 917 operated over the upper winding independent of the continued existence of ground potential on the test lead of the called line, after the series auxiliary relay 919 has responded to the impulse delivered upon the restoration of relay 913. Upon the restoration of release relay 914 an impulse is delivered through contacts of release-auxiliary relay 915, through contacts of busy-test relay 917, and over busy conductor 953 for busy relay 704 in the local connector. Busy relay 704 responds by closing a locking circuit for itself to the grounded holding conductor 623.

A moment later, after sufficient time has been allowed for the above-mentioned busy relay 704 to operate and close its locking circuit, the first release auxiliary relay 915 restores and opens the initial circuit of the busy relay 704 at its upper armature, while at its inner upper armature it closes a circuit through contacts of the still-operated second auxiliary-release relay 916 for operating the cut-off relay 702. This circuit is over cut-off conductor 955 as hereinbefore traced, except that it now includes the operated armature of busy-test relay 917 instead of the operated armature of idle-test relay 921. Cut-off relay 702 operates and as previously described brings about the restoration of connecting relay 703 to disassociate the common equipment unit CE1 from the local connector. A moment later, relay 916 restores. This, along with the restoration of the remaining relays of the unit CE1, completes the clearing out of this unit as previously described.

In the local connector LOC, with cut-off relay 702 operated the further maintenance of ground potential on hold conductor 623 is under the direct control of the contacts of release relay 701. The pick-up and interrupter-start leads 735 and 736 are maintained disconnected at contacts of the actuated busy relay 704. The busy-tone lead 726 is connected to the upper taking conductor 621 at the upper contacts of busy relay 704, by way of the current-limiting condenser 727, and a return path to ground is provided over the lower talking conductor 622 through additional contacts of busy relay 704 and condenser 728. It is to be noted that ground potential is prevented from being applied by way of the C wiper 700 to the C lead of the called line upon the operation of cut-off relay 702, as the conductor extending to the C wiper 700 passes through the normally closed contacts of the now-actuated busy relay 704.

When the calling subscriber, being informed of the busy condition by the busy-tone signal applied as above pointed out, replaces his receiver, the restoration of line relay 706 permits release relay 707 to restore, whereupon the finder-connector link and the calling line circuit are cleared out as hereinbefore described.

Giving multi-line service

The system disclosed is so arranged that any subscriber may be given service over each of two or more available subscriber lines. Although it is more likely that the multi-line service will be given by way of individual lines or at least by way of lines with a smaller number of stations connected thereto, the circuit arrangements are such that it is possible to give multi-line service over party lines to any one of the stations on a party line, regardless of the signalling code used, in the event that another line is available for extension to the subscriber's premises. Since the most com-

5 plicated circuit condition that arises in the common-equipment units relative to the giving of the multi-line service arises when the code assigned is a two-digit code for party line use, the multi-line arrangement will be described with reference to its functioning in this situation. For this purpose it will now be assumed that the subscriber at party-line substation **400** is provided with multi-line service and that a second line extends
10 from the exchange to his premises and has a substation connected thereto. Of necessity, the same code is used for signalling the multi-line subscriber, over each line. Additionally, it is essential that the two lines be reached from the
15 same level of the connectors, and it is moreover preferable that they be connected to adjacent terminals in the connector bank. It will be assumed that the second line through which service is given to the subscriber over substation **400** is connected to the next succeeding set of terminals in the connector bank from the illustrated terminal set **450**, through which the line TPL is
20 reached.

For the purpose of description, it will be assumed that the subscriber at substation 300 has initiated a call and has given the operator the number of the subscriber at substation 400, and that the operator has called this number and that the line TPL tests busy at the time the wipers 25 of connector LOC arrive thereon. It will be recalled that this condition results in the operation of busy-test relay 917 through contacts of series auxiliary relay 919, at the end of the 30 second digit and in the closing of a local locking circuit for the lower winding of busy test relay 917 upon the restoration of series auxiliary relay 919 at the end of the second or units digit. It will be recalled also that an application of busy-tone current is made at the upper contacts of 35 busy test relay 917 to the talking connection so that the busy tone is heard by the calling subscriber and by the operator. When the subscriber being called is one having multi-line service, however, the operator does not immediately 40 restore her key and allow the connection to clear out as in the previous description. Instead, she 45 dials the party selecting portion of the number, disregarding the busy tone signal, following which she dials an additional digit 1 so as to cause the 50 wipers of the connector to advance to the next succeeding line.

It will be recalled that the lower winding of units-digit relay 924 is operated in multiple with the lower winding of busy-test relay 917 through 55 the lower contacts of series-auxiliary relay 919, when the series-auxiliary relay restores. Its operating circuit includes contacts of relays 926 and 928. Relay 924 disconnects the common operating conductor 934 from the rotary conductor 951 and transfers it through contacts of relays 926 and 928 to party-selector operating conductor 958. As a result, when the next digit is dialled, the 60 first party digit 1, the resulting impulse is transmitted over conductor 958 to the operating magnet 743 of the party selector PS1, thereby advancing the wipers 741 and 742. It is to be noted that relay 924 remains operated in parallel with the 65 lower winding of busy-test relay 917 through the lower contacts of relay 924 when series-auxiliary relay 919 is reoperated upon the dialling of the 70 party-selecting digit.

As previously explained, relay 925 is operated when relay 919 operates at the beginning of the first party digit; and relay 926 operates in series with relay 925 and in the locking circuit of the

latter relay when relay 919 restores at the end of the digit. At its upper contacts, relay 926 disconnects the common conductor 934 from the party-selector operating conductor 958, unless the code-group pilot relay 920 operates to shunt the upper contacts of relay 926, as it does not in the manner hereinbefore pointed out because the first party-selecting digit dialled is the digit 1, and code-group relay 713 and code-group-pilot relay 920 are operated in series with each other as a result. It is to be recalled that code-group-pilot relay 920 locks itself at its inner lower contacts to the grounded conductor 935.

In addition, the lower contacts of relay 926 break the circuit of the lower winding of units-digit relay 924 and restores the units-digit relay unless these contacts are shunted by the lower contacts of code-group pilot relay 920, as they now are. It is to be noted that the upper end of the core of relay 926 is provided with a conducting collar, as is indicated by the solid upper portion of the relay. This collar renders the relay sufficiently slow in operating that code-group-pilot relay 920 has time to operate and shunt the lower contacts of relay 926 before relay 926 operates to open the circuit of units-digit relay 924.

When the second and final party-digit is dialled, the party-digit 5 in the assumed example, an additional series of five impulses is transmitted from the common impulse conductor 934, over the party-selector operating conductor 958 to the party selector PS1 to cause this selector to advance five additional steps and thereby bring the effective wiper 742 into bridging engagement with the contact pair to which the lower code lead 747 is connected.

In the common-equipment unit CE1, relay 927 is operated at the beginning of the final party digit, and relay 928 operates in the locking circuit of relay 927 at the end of the second party digit. Upon operating, relay 928 opens the party-selector operating conductor 958 at the upper contacts, while at its lower contacts it disconnects the lower winding of relay 924 and permits this relay to restore. Upon restoring, units-digit relay 924 again transfers the operating conductor 934 back to the rotary conductor 957.

As a result, when the operator next dials the special advancing digit 1, the single impulse generated by this digit is transmitted from the common impulse conductor 934 and over rotary conductor 957 to the rotary magnet 717 of the local connector LOC. This causes the wipers 700 to advance one step into engagement with the terminal through which the next succeeding line is reached. From this point, the operations depend upon whether this next line is busy or idle. If this line is busy, busy-test relay 917 in the common equipment unit remains operated; the busy tone continues to be given and connection to the line is desired. In the event that the subscriber being called has still a third line, the operator may again dial the special advancing digit 1 to cause the wipers of the connector to advance another step, whereby this third line is tested. This operation may be continued until an entire level of bank contacts is tested, if the occasion demands.

For the purpose of illustration, it will now be assumed that the next succeeding line is idle instead of being busy as above mentioned. Under this assumption, when series-auxiliary relay 919 reoperates upon the dialling of the special advancing digit 1 and disconnects the lower winding of busy test relay 917 from the local locking circuit and reconnects it through contacts of idle test 70 75

relay 921 to the C wiper 700 by way of test conductor 960, busy-test relay 917 restores, thereby opening a further point in its local locking circuit. Under this condition, when series relay 919 restores, the lower winding of idle-test relay 921 is energized over test conductor 960 and by way of the C wiper 700 in series with the cut-off relay of the called line. Relay 921 closes a locking circuit for its upper winding to conductor 935; prepares to transmit an impulse over cut-off lead 955; and it by-passes its own lower winding and the contacts of series-auxiliary relay 919 by connecting the grounded conductor 935 to the test lead 960, whereby ground potential is applied directly to test lead 960 and the connection is prevented from being broken when relay 919 next operates.

From this point, the operation is as hereinbefore described; the common equipment CE1 is cleared out when the operator restores her answering key K1, and the local connector LOC is caused to signal the desired substation on the called line, and to complete the talking circuit when the called subscriber answers.

Local calls to a four-party line

In order to explain how calls are completed to four-party lines, such as the four-party line FPL, Fig. 3, and the desired substation is signalled to the exclusion of the other three substations on the line, it will be assumed that the subscriber at substation 400 of the ten-party line TPL desires to converse with the subscriber at substation 300 on the four-party line FPL. It will be understood, of course, that when the four-party line FPL is fully equipped with four substations, two of the ringers are connected between one conductor and ground, while the other two ringers are connected between the other conductor and ground and that the two ringers connected between either conductor and ground are oppositely biased. It will be understood further that the usual arrangement is employed at the substations, there being a relay at each substation bridged across the line in series with a condenser so that it operates responsive to each application of alternating current to connect the associated ringer between ground and the chosen side of the line, whereby there is normally no direct current path through the ringers. Preferably, the ringers are of high resistance or else have a relatively high-resistance element connected in series so as to limit the flow of direct current during ringing to thereby permit an increased flow for the operation of the ring-cut-off relay when the called subscriber replies.

It will be assumed that, when the subscriber at substation 400 removes his receiver, the finder F1 is the one preselected by the distributor D, and that the common equipment CE1 is idle and is therefore taken for use by the local connector LOC when the finder F1 finds the line circuit LC2, Fig. 4. These operations are the same as those described in connection with the removal of the receiver at substation 300 except that the wipers 600 of the finder F1 finds the terminals 451 instead of the terminals 351, as in the previous description.

When the operator replies and is told of the desired number, she dials the digits in the number, first causing the wipers 700 of the local connector LOC to be raised opposite the desired level and then rotated into engagement with terminals 350 or multiples thereof, following which the operator dials the final digit, the party selecting digit, and then clears out her equipment and

permits the common-equipment unit CE1 to clear out.

Assuming that the subscriber at substation 300 is the first subscriber on the four-party line, the party digit assigned to this station is the party 5 digit 1. Therefore, the wipers 741 and 742 are advanced into engagement with the seventh set of contacts by the operation of magnet 742 responsive to the impulses in the party selecting digit. The seventh-position contacts of the wiper 10 741 are not connected, but wiper 742, in its seventh position, bridges contacts which close a circuit for the positive-generator relay 714. With this relay in operated position, the upper terminal of the upper winding of ring-cut-off relay 15 710 is disconnected from its normal association with the negative wiper 700 and is transferred into connection with the positive-generator lead 733. In addition a connection is prepared from the lower terminal of the upper winding of ring-cut-off relay 710 to the negative wiper 700 at contacts of relay 714, preparatory to transmitting ringing current over the negative side of the called line through the upper winding of ring-cut-off relay 710. As a result, assuming the 25 called line to be idle, when the common-equipment unit is cleared out, pick-up relay 711 operates shortly to complete the ringing circuit. Henceforth, each time the ringing interrupter (not shown) applies positive superimposed ringing current to the positive-generator lead 733, ringing current flows through contacts of the positive-generator relay 714, upper winding of ring-cut-off relay 710, contacts of pick-up relay 711, additional contacts of positive-generator relay 714, contacts of line-reversing relay 715, upper contacts of ring-cut-off relay 710, and contacts of pick-up relay 711 to the negative conductor of line FPL, by way of the negative wiper 700. The biased ringer at substation 300 is there- 40 operated between the negative conductor of the line and ground.

The flow of current through the upper winding of ring-cut-off relay 710 during the ringing operation is insufficient to cause the relay to 45 operate, as the relay is specially adjusted so as not to operate with this amount of current flowing.

When the subscriber at substation 300 removes his receiver and thereby closes the usual low-resistance, direct-current bridge across the conductors of the line FPL, the flow of current over the ringing circuit about traced and over a return path from the positive conductor of the line, to ground at the upper contacts of line-reversing relay 715, is sufficient to operatively energize the upper winding of relay 710. Relay 710 closes a locking circuit for its lower winding; opens the ringing circuit; and completes the talking circuit.

Conversation may now proceed.

The established connection is cleared out as hereinbefore described when the calling subscriber replaces his receiver.

Signalling the other substations on a four-party line

When the connector LOC is in use in a call to the second substation on a four-party line such as the line FPL, Fig. 3, the party-selecting 70 digit dialled is the digit 8. In this case, wiper 742 bridges its eight-position contacts and thereby closes a circuit for the negative-generator relay 712. Then, when pick-up relay 711 operates, ringing current is transmitted from the 75

negative-generator lead 734 through contacts of the pick-up relay 711, the upper winding of ring-cut-off relay 710, and thence through contacts of relays 714, 715, 710, and 711 to the negative conductor of the called line, by way of the negative wiper 700. It is to be noted that the upper winding of ring-cut-off relay 710 is included in the ringing circuit in reverse direction when the positive-generator relay 714 is operated, but not when the negative generator relay 712 is operated. This reversal is made in the case of applying ringing current from the positive-generator lead 733 in order to maintain the polarity of magnetization of the upper winding of relay 710 always in the same direction, for when this winding is energized it closes a locking circuit for the relay through the lower winding, and the polarity of the two windings must therefore agree.

It is to be noted that, when the third substation on the four-party line is called, the positive-generator relay 714 is operated through the ninth-position contacts of relay 742, as it was in the seventh position contacts of this wiper, and that the negative-generator relay 712 is operated through the tenth-position contacts of wiper 742 when the fourth substation on the line is signalled, as in position eight of wiper 742, when the second substation on the line is to be signalled. In order to distinguish between the seventh and eighth positions of the party selector PS1 on the one hand, and the ninth and tenth positions of the party selector on the other hand, the line reversing relay 715 is connected to the ninth- and tenth-position contacts of wiper 741 so that it operates when the party selecting digit dialled is either a 9 or a 10 to reverse the connection between the ringing circuit and the line conductors. With line-reversing relay 715 operated, it is to be noted that the transmitted ringing current flows out by way of the positive wiper 700, and that the return circuit to ground is by way of the negative wiper 700. In this way, the third and fourth substations on the line are signalled in exactly the same way as the first and second substations except that the ringing current is applied to the other talking conductor by the action of line-reversing relay 715.

50 Locking defective lines out of service

Arrangements are provided for automatically locking defective lines out of service. In order to describe this feature, it will be assumed that the line of substation 300 becomes sufficiently defective that line relay 301 operates thereover due to a defect on the line instead of responsive to a call. It may be assumed that the finder F1, Fig. 6, is the one which responds to the call and that the common equipment CE1 is the one taken for use. When the operator responds, she receives no answer from the calling line and she therefore clears out her connection without dialling. In this event, neither of the test relays 917, and 921 is operated. Therefore, when release-auxiliary relay 915 restores, it closes a circuit through contacts of release-auxiliary relay 916, through contacts of relays 917 and 921, over the forced release conductor 954, and through contacts of connecting relay 703, for the forced-release relay 708. Relay 708 thereupon operates and removes ground potential from holding conductor 623, unlocking and restoring all previously actuated relays of the finder-connector link. The connector is released when relay 701 re-

stores, and the finder F1 clears out responsive to the restoration of relay 601 and the resulting closure of the circuit of release magnet 605.

In the line circuit LC1, associated with the assumed defective line FPL, cut-off relay 302 restores responsive to the restoration of switching relay 601 of the finder F1, it opens the holding circuit of the slow-acting lock-out relay 303, in addition to reconnecting the line relay 301. Since the line is defective, line relay 301 immediately operates upon being reconnected by the restored cut-off relay 302, and closes a locking circuit at its lower contacts for the still operated slow-releasing lock-out relay 303. Lock-out relay 404 remains operated in its locking circuit, including the lower contacts of line relay 301, until such time as the defective line becomes cleared of its defect, at which time relay 303 falls back responsive to the restoration of line relay 301.

It is to be noted that, while lockout relay 303 is operated, it maintains the start conductor 361 disconnected at its lower armature, and that it maintains cut-off relay 302 disconnected from the C terminal 351 so as to prevent a finder operating in search of another line from finding the line FPL because of the closed condition of the upper contacts of line relay 301. It will be appreciated, of course, that this arrangement is especially advantageous in an unattended, remotely controlled exchange, as the automatic locking-out of the defective lines prevents the useless tying up of finder-connector links, which if allowed to take place may seriously impair the service even though only a small number of lines were defective, as only from seven to ten of these links are ordinarily provided for a 100-line system.

Calls to vacant lines

In the event that a subscriber inadvertently calls an unassigned number, and the resulting digits dialled by the operator causes the wiper of a connector such as LOC, Fig. 7, to be advanced to a vacant set of bank terminals, neither of the test relays 917 and 921 of the common equipment until CE1 (assuming this common equipment CE1 is used) is able to operate, as no connection is made over the test conductor 960 and the C wiper 700 by way of the C lead of the unassigned set of terminals. In this event, when the operator clears out the common equipment after dialling the number, forced release conductor 954 is momentarily grounded instead of cut-off conductor 955. As a result, forced-release relay 708 of the local connector is operated instead of cut-off relay 702. When forced release relay 708 operates, it causes the finder-connector link to clear out as described.

In addition, the calling line is locked out of service in the manner described, which locked condition persists until the calling subscriber replaces his receiver and allows the line circuit to return to normal condition.

By the described arrangement, a finder-connector link is immediately returned to common use when it is inadvertently operated to make a connection with an unassigned set of bank contacts. This arrangement promotes the more efficient use of the finder-connector links than would otherwise obtain.

Answer failure

The way in which answer failures are provided for will now be described. For this purpose, it

will be assumed that a call is received from a subscriber line as hereinbefore described; that the link of Figs. 6 and 7 is taken for use; that through this link the common equipment CE1 is taken for use; and that the operator in Mount Morris fails to answer within a reasonable time. The failure being caused, for example, by an operating-trunk failure, or by some equipment failure in the Mount Morris exchange. Under this condition, the previously mentioned answer timer, composed of relays 909-911, is permitted to operate fully under the control of the associated timer T, as will now be explained.

It will be recalled that start relay 908 operates when the common equipment unit CE1 is first taken for use. Start relay 908 connects ground potential to start conductor 931 by way of contacts of cut-off relay 909, and it connects pick-up conductor 932 through contacts of relay 909 to the winding of pick-up relay 911. The timer T, which may be of well-known construction, is started into operation responsive to the placing of ground potential on conductor 931, and it shortly grounds the pick-up lead 932, causing a circuit to be closed through contacts of relay 909 for pick-up relay 911. Pick-up relay 911 operates and locks itself to ground through contacts of cut-off relay 909, opening its initial circuit. Pick-up relay 911 also prepares a circuit for the upper winding of alarm relay 910 by way of alarm conductor 933, associated with the timer L.

After an interval of time has elapsed sufficiently long to enable the operator in Mount Morris to answer the call in the regular way, and in the event that cut-off relay 909 has not been operated to restore relay 911 as a result of the usual response of the control operator, ground potential placed on alarm conductor 933 by the timer energizes the upper winding of alarm relay 910 through contacts of pick-up relay 911. Alarm relay 910 locks itself at its inner contacts to ground through contacts of the cut-off relay 909, while at its lower contacts it places ground potential on the alarm conductor 949. The conductor is assumed to extend to an alarm device which may be mounted on the outside of the building housing the equipment, or it may be located a short distance away on the premises of some local person to whom is entrusted the duty of responding to an alarm condition. Ground potential is maintained on alarm conductor 949 and relays 910 and 911 remain locked until the call is answered and cut-off relay 909 operates as a result.

A similar conductor to alarm conductor 949 is provided in the common equipment CE2, and these two conductors are customarily connected together and extended to the same alarm-signalling device, whereby the answer-failure alarm 60 is sounded whenever either of the two common equipment units is taken into use and the operator fails to answer within a predetermined time.

Using the local control set LCS

A local control set LCS, Figs. 9 and 17, is provided and is connected to the two common equipment units CE1 and CE2 as indicated in Fig. 17 and in part 1 of Fig. 9, the local control set LCS being indicated in Fig. 9 by means of a small dotted rectangle for the purpose of better illustrating how this control set is connected with the common equipment units CE1 and CE2.

It may be assumed now that a call over one or the other of the common-equipment units 75 CE1 and CE2 has remained unanswered for a

sufficient length of time that the answer-failure alarm signal has been caused to operate as above pointed out. In this event, the local person entrusted with the local operation of the remotely controlled exchange may proceed to the local-control set housed in the exchange building and take over the control of handling the calls, either partially or fully.

Upon examining the local control set LCS, as illustrated in Fig. 17, it is observed that this control set includes substantially a standard automatic telephone, minus the usual bridged ringer, as it has switchhook contacts 1909, a transmitter T, a receiver R, and a dial-type calling device 1710 associated with the negative and positive talking conductors 1705 and 1706. The local control set includes, in addition, the signal buzzer 1708, connected between the ungrounded negative pole of the exchange battery and the signal conductor 1707, as well as the control keys CK1 and CK2, interconnected with conductors 1701-1704. The local control set LCS is interconnected with the common equipment units CE1 and CE2, as indicated in Figs. 9 and 16.

It may be assumed first that the local operator 25 at the Leicester exchange, upon being informed by the alarm signal of an answer failure, desires temporarily to take over the control of the Leicester exchange only partially under the possible assumption that the existing trouble condition may 30 be shortly relieved. In this event, the local operator may operate the partial-control key CK1 in the desired direction. Assuming that the unanswered call is being held on common-equipment unit CE1, and that it is from this common-equipment unit that the alarm signal has been given, by way of alarm conductor 949, when the partial-control key CK1 is operated to the left, the left-hand contacts of this key apply ground potential to the No. 1 transfer conductors 1702 40 thereby extending ground potential by way of conductor 947, Figs. 17 and 9, to the winding of transfer relay 905. Transfer relay 905 thereupon operates and transfers the talking conductors 45 associated with the common equipment unit CE1 through the illustrated terminals to the talking conductors 1705 and 1706 of the local-control set LCS. Relay 905, at its lower contacts, now closes a circuit over conductor 946 and by way of signal conductor 1707 for the signal buzzer 50 1708. This circuit includes contacts of start relay 908 in the common equipment unit and contacts of the unoperated release-auxiliary relay 916. As a result of the closure of this circuit, the signal 55 buzzer 1708 on the local control set sounds, indicating to the operator that the common equipment CE1 is holding an unanswered call.

In order to answer the call, the local operator removes the receiver R from its hook, permitting hookswitch contact 1909 to close, thereby bridging the receiver R and transmitter T, in series with the impulse contacts of the calling device 1710, across the negative and positive talking conductors 1705 and 1706. This action closes a circuit through contacts of the operated transfer 65 relay 905 and through windings of repeating coil 947 for line relay 913. Relay 913 now operates with the same results described in connection with the response of the operator in the Mount Morris exchange. The actuation of signal buzzer 70 1708 is terminated when the circuit thereof is opened at the lower contacts of release-auxiliary relay 916. In addition, cut-off relay 909 is operated through the contacts of release relay 904 to disconnect the timer T and to unlock and restore 75

the alarm and pick-up relays 910 and 911, thereby permitting the answer-failure alarm signal to cease its operation, unless there is also an unanswered call waiting on the common equipment 5 CE2.

The local control operator may now converse with the calling subscriber and ascertain the desired number. She may dial the number by means of the calling device 1710. The lower contacts of this calling device are arranged to close as long as the calling device is in an off-normal position, thereby shunting the transmitter and receiver to remove them from the dialling circuit and to prevent undesirable clicking from being heard in the receiver R. 10

When she has completed the dialling of the desired number, the local control operator may replace her receiver, whereupon contacts 1909 separate, permitting line relay 913 to restore and 15 allow the common equipment unit CE1 to clear out. 20

In the event that the local control operator desires to take over the partial control of the common equipment unit CE2, she may now actuate the control key CK1 to the right, causing contacts thereof to place ground potential on the 25 No. 2 transfer conductor 1704. This operates the relay in the common equipment unit CE2 which corresponds to transfer relay 905 of the common 30 equipment unit CE1, with the results as described.

It is to be noted that in the event of the failure of one of the operating trunks, the local control operator may leave the partial control key CK1 thrown in the corresponding position and thereby 35 answer locally and locally control the extending of all calls received over the corresponding common equipment unit, while the calls which are received on the other common equipment unit may pass over the remaining operating trunk to 40 the control switchboard in the Mount Morris exchange.

The local operator assumes full control

It will now be assumed that the local operator deems it desirable to take full control of the setting up of connections in the Leicester exchange. She may do this by associating the local control set LCS with either of the two common equipment units, at the same time removing the other 45 common equipment unit from service and thereby preventing calls from passing over the associated operating trunk, in which case all calls are received on the local control set LCS. It will be assumed that the local control operator 50 desires to use the common equipment CE1 when she takes full control of the setting up of connections (the choice is arbitrary unless one of the common equipment units or associated equipment is defective). In this event, the operator actuates the full-control key CK2 to the left, thereby placing ground potential on transfer conductor 1702 which is extended through transfer conductor 947 to transfer relay 905 of the common equipment CE1. This transfer relay 905 55 operates and transfers the talking conductors of the common equipment unit CE1 from the operating trunk OT1 to the local control set LCS. At the same time the lower left-hand contacts of the full-control key CK2 place ground on the 60 No. 2 switching conductors 1703, extending ground potential over switching conductor 943', Figs. 17 and 9, to terminals 942' and 943' of the common equipment CE2, corresponding to terminals 942 and 943 of the common equipment 65 CE1. As a result, the relay in common-equip- 70

ment unit CE2 corresponding to relay 901 of CE1 is operated to indicate to the distributor D, Fig. 8, that the common equipment CE2 is not to be taken for use. Under this condition, all calls are directed to the common equipment CE1 and none are therefore transmitted to the common equipment CE2, as the No. 2 selecting conductor 962 is maintained open at the contacts of the relay in the common equipment unit CE2 which corresponds to relay 901. In this way, each originated 10 call is received by way of the common equipment CE1 at the local control set LCS. 15

It is to be noted that with the full-control key CK2, Fig. 17, thrown to the left and transfer relay 905 operated, each time start relay 908 15 operates it closes a circuit over conductors 946 and 1707 for the signal buzzer 1708, notifying the local control operator of the call, which she may answer by removing the receiver R from the hook and permitting switchhook contacts 1909 to 20 close. 25

When the need for the local control of the Leicester exchange has disappeared, the local control operator may restore the key CK2, whereupon transfer relay 905 clears out, and the seizing 25 control relay in the common equipment unit CE2 corresponding to relay 901 of CE1 restores. From this point, the originated calls are handled over the operating trunks OT1 and OT2, as herein-before described. 30

An all-links-busy condition

The operations which occur when all of the finder-connector links in the Leicester exchange become busy will now be described. The busy-common conductor 861, through which actuating ground potential is applied to the lower terminal of the winding of switching relay 802, is maintained grounded normally at each of the unoccupied finder-connector links. For example, 40 when the finder F1 is in normal position and the start relay 602 thereof is not operated, ground potential is applied from the finder F1 to busy-common conductor 861 through contacts of start relay 602 and off-normal contacts 666, in normal position. With ground potential on busy common conductor 861, a contact in the bank of test wiper 821 associated with a contact set not used for extending connection to the finders, such as F1, is maintained grounded. This ground connection is opened when start relay 602 operates responsive to the finder F1 being taken for use, and the ground connection is maintained open at off-normal contact 606 after the finder has 45 operated and start relay 602 is restored, until the 50 finder is restored to its normal position, after being used. The removal of ground potential at a finder from the busy-common conductor 861 is without effect, however, as long as ground potential remains on this conductor at one or 55 more other finders. However, when all of the finders but one are in use and ground potential is being held on conductor 861 at one finder only, and this finder is then taken for use, conductor 60 861 becomes devoid of direct ground connection. 60 Then, when the wipers 821-825 of the distributor D are started rotating in search of an idle finder, no idle finder can be found, as they are all in use. Wiper 821, however, finds an ungrounded contact when it encounters the contact to which the now-ungrounded, busy-common conductor 65 861 is connected. The wipers of the distributor D therefore stop with wiper 821 in association with conductor 861. A circuit is prepared for 70 busy common relay 851 in series with operating 75

magnet 800 of the distributor D, but nothing occurs as a result of this for the time being as the operating trunk OTI and the common equipment CEI are in use. As soon after this condition 5 obtains as the common equipment unit CEI becomes idle and start relay 908 and release relay 914 are restored, ground potential is placed on the upper terminal of the winding of busy common relay 851, closing a circuit for this relay by way of the branch of busy common conductor 861 extending to contacts in the bank of wiper 821, wiper 821, contacts of switching relay 802, interrupter contacts of magnet 800, and the winding of operating magnet 800 to the ungrounded pole of the exchange battery. Busy 10 common relay 861 operates in this circuit, but magnet 800 does not operate because of the relatively high resistance of relay 861. It is to be noted that switching relay 802 cannot operate 15 at this time even though start relay 801 operates, as it is short circuited by the connection made with busy common conductor 861 through wiper 821.

When busy common relay 851 operates, it 20 closes a locking circuit for itself at its inner upper contacts independent of the contacts of relays 908 and 914; it prepares a busy tone connection to the talking circuit at its upper contacts, and at its lower contacts it closes a circuit 25 for the lower winding of call relay 855 by way of contacts of start and auxiliary release relays 908 and 916. Call relay 855 thereupon operates and closes a locking circuit for its upper winding through the upper contacts of cut-off relay 854 30 as well as through contacts of the operated relay 851. At its two uppermost armatures, call relay 855 completes the prepared busy-tone-signalling circuit from busy-tone conductor 858 to a talking conductor, and completes ground-return circuit 35 through contacts of relay 853 and blocking condenser 860; it prepares a circuit for cut-off relay 854 at its inner lower contacts; and at its middle lower armature it closes a circuit from ground at the inner lower contacts of busy-cut-off relay 852 for operating signal relay 906, by 40 way of contacts of signal-cut-off relay 907. Signal relay 906 thereupon operates and momentarily opens the negative conductor of the operating trunk OTI to cause the Mount Morris operator 45 to be signalled over the operating trunk, and it closes a circuit for the slow-operating signal-cut-off relay 907. Relay 907 operates after a slight interval and closes a locking circuit for 50 itself, opening the circuit of signal relay 906 55 and permitting it to restore.

In this way, the Mount Morris operator is signalled over the operated trunk OTI, and she responds to the signal as in any other call, whereupon line relay 913 and the release and 60 auxiliary relays 914-916 respond. The operator, however, at this time hears the busy-tone signal caused by the connection to the lower talking conductor (to the right of repeating coil 65 947) from the busy tone lead 958, the upper 70 talking conductor being grounded through condenser 960 to form a return path for the busy signalling current.

Upon being thus informed that all of the local 75 links in the Leicester exchange are in use, the operator may proceed to monitor or supervise these links successively, and she may release any link which is being held over which conversation is not taking place. A link may be held without conversation taking place because a calling line has become sufficiently defective after

a connection has been set up that the line relay of the connector does not restore when the calling subscriber hangs up, and it may be held without conversation in the event that the calling subscriber has neglected to replace his receiver after 5 he has finished a conversation.

In order to make monitoring connection with the local links in the Leicester exchange, the operator dials a preliminary digit, the digit 1, for example, following which she dials the digit 1 10 repeatedly, each time operating the supervising switch SS to a different position to make talking connection with a different one of the local links each time an additional digit 1 is dialed, until all the local links have been supervised. 15

When the preliminary digit 1 is dialed, the tens-digit counting relays 922 and 923 respond as hereinbefore described, and relay 923 becomes operated to place the operating magnet of the supervising switch SS under the control of line 20 relay 913.

At the same time, the impulse delivered by the momentary restoration of line relay 913 passes through contacts of release relay 914 to the upper winding of busy-cut-off relay 852, by way of 25 the inner lower contacts of call relay 855 and the inner lower contacts of the operator busy-common relay 851. Relay 852 locks itself to the grounded conductor 930 at its middle lower armature; it opens the locking circuit of signal-cut-off relay 907 at its inner lower armature (start relay 908 is not in an operated position at this time); at its lower armature it prepares a circuit for the operating magnet of the supervisory switch SS, associated with the common 30 equipment unit CEI, Fig. 9, part 1; and at its upper armature it breaks the circuit through which the busy-tone current was supplied from lead 858, thereby terminating the application of 35 busy tone.

Each time the digit 1 is dialled subsequently, an impulse is delivered by line relay 913 through the lower contacts of release relay 914, lower contacts of busy-cut-off relay 852 in multiple with the lower contacts of the restored relay 907, 45 lower contacts of tens-digits counting relay 923, to the operating magnet of the supervising switch SS. By the operation of the operating magnet of switch SS, the wipers R, C, negative, and positive of this switch are advanced one step, 50 and the negative, positive, and C wipers thereof make connection through contacts and bank conductors with negative and positive conductors 621 and 622, and with the forced-release conductor 723. 55

Assuming that the operator finds that no conversation is being conducted over the finder connector link of Figs. 6 and 7, and that this link is being held from a calling line (the line FPL, Fig. 3, for example) either because the line has become defective after a connection is set up, or because the calling subscriber has neglected to replace his receiver, the operator may force the release of the finder connector link. To do this, the operator momentarily actuates 65 the supervisory-release key K2, Fig. 10, momentarily unbalancing the current flow over the operating trunk OTI sufficiently to bring about an operation of the differential supervisory-release relay 912. Relay 912 momentarily applies 70 ground potential through the C wiper of the supervisory switch SS, and the bank terminal with which it is in engagement, to the forced-release conductor 733 of the connector LOC. Forced-release relay 708 is thereupon operated 75

over conductor 733 to remove ground potential from holding conductor 623 and thereby cause the link to clear out as hereinbefore described. As pointed out hereinbefore, lock-out relay 303 of the offending line circuit LC1 remains energized in a self-locking circuit which is closed as soon as line relay 301 operates responsive to being reconnected upon the restoration of cut-off relay 302, which takes place in the usual manner when the connection is cleared out.

The operator may continue the supervising operation until she has monitored on each of the local links, clearing out any one of them found to be held from a defective line.

As soon as a link has been rendered idle, ground potential is restored to busy-common conductor 861, which operation results in the immediate advance of the distributor D from the all-links-busy position, and resulting in the restoration of the busy common relay 851. Busy-cut-off relay 852, however, remains operated in its locking circuit over the grounded conductor 930. Upon the delivery of the next impulse at the contacts of line relay 913 (either upon the dialling of the next digit 1 or upon the clearing-out operation) alarm-cut-off relay 854 is operated through contacts of the locked call relay 855 and through contacts of the now restored busy common relay 851. Upon operating, relay 854 opens the locking circuit of call relay 855 at its upper contacts, permitting call relay 855 to restore.

When she has completed her supervising operations, the operator in the Mount Morris exchange restores the answer key K1, Fig. 10, opening the bridge from across the conductors of the operating trunk OT1 and permitting the common equipment unit CE1 to clear out. When ground potential is removed from locking conductor 930 at contacts of release-auxiliary relay 916, the locked busy cut-off relay 852 is permitted to clear out along with the relays in the common equipment unit CE1.

The supervisory switch SS is restored to its normal position when release auxiliary relay 916 restores and closes a restoring circuit for the operating magnet through the R wiper of the supervising switch, by way of off-normal contacts in the associated bank and the self-interrupting contacts of the operating magnet.

50 Voluntary supervision of the local links

At regular intervals, an operator in the Mount Morris exchange may supervise the local links by throwing the answering key K1 to take the operating trunk OT1 in use at a time when no call has been received thereover. At this time, start relay 908, signal relay 906, and signal cut-off relay 907, are inactive and the negative and positive wipers of the supervising switch SS remain connected to the talking conductors of the operating trunk OT1 by way of the repeating coil 947, and are not disconnected by relay 907 as they are in the normal answering of a call. In addition, with signal cut-off relay 907 in an unoperated condition, the lower contacts thereof have a circuit prepared for the operating magnet of the supervising switch SS, which circuit is completed as soon as the operator dials a preliminary digit and thereby causes the tens-digit counting relays 922 and 923 to operate.

Transmitting an alarm signal

The way in which an alarm signal is transmitted from the remotely controlled Leicester exchange to the operating Mount Morris exchange

over the operating trunk OT1 will now be pointed out. In the miscellaneous relay group MG, Fig. 8, it will be observed that the power board is indicated by rectangle 862. The contacts 863 are mounted on the power supply switchboard panel and are arranged to become closed whenever there is an abnormal condition in the exchange, such as a blown fuse, failure of the battery-charging apparatus to start, and so forth. When the contacts 863 close, alarm-signal relay 853 is operated through contacts of alarm-cut-off relay 854. At its upper armatures, relay 853 changes over the associated signal conductors to prepare for the transmission of a signal from the ringing generator lead by way of the limiting condenser 859 upon the response of the operator, while, at its lower contacts, relay 853 closes a circuit for the lower winding of call relay 855 through contacts of start relay 908 and release auxiliary relay 916. Upon the operation of call relay 855, the operator is signalled over operating trunk OT1 in the manner hereinbefore pointed out, and when she replies she is notified of the fact that an alarm condition exists because of the generator signal applied through contacts of the operated alarm-signal relay 853.

When the connection is cleared out an impulse is delivered by relay 913 over conductor 934 to actuate alarm-cut-off relay 854 and lock it through contacts 863. Relay 853 thereupon restores.

Removing an operating trunk from service

Provisions are made whereby either operating trunk may be removed from service, leaving the other operating trunk in service to handle all calls originated in the remotely controlled exchange. This may be effected from either the Mount Morris or the Genesee exchange upon the dialling of a pre-assigned number into any of the connectors of the Leicester exchange. The withdrawing from service and returning to service of the operating trunk OT1 is controlled by make-busy relay 902, while a similar make-busy relay is provided in the common-equipment unit CE2 for a corresponding purpose. The C terminal 81 associated with the upper winding of make-busy relay 902 is representative of the C terminal in the bank of any connector reached when the number 81 is dialled, while the C terminal 82 associated with relay 902 is representative of the terminal reached by the C wiper of any connector when the number 82 is dialled.

Assuming now that the number 81 is dialled into any connector in the Leicester exchange, the C wiper thereof is brought into engagement with the illustrated C terminal 81, or a multiple thereof, extending ground potential to the upper winding of make-busy relay 902. Relay 902 thereupon operates and closes a locking circuit for its lower winding in series with the associated resistor. At its lower contacts, relay 902 closes a circuit for seizing-control relay 901, causing this relay to operate and shift the seizing-control conductor from No. 1 conductor 961 to the No. 2 conductor 962, by way of the common-equipment unit CE2.

Since this make-busy operation may occur at a time when a call is waiting on the common-equipment CE1, the forced-clear-out relay 903 and associated cut-off relay 904 are provided. At the upper contacts of make-busy relay 902, a circuit is closed for the forced-clear-out relay 903. Relay 903 operates and closes a circuit for cut-off relay 904. Cut-off relay 904 operates and locks itself to contacts of relay 902, disconnecting re-

lay 903 and permitting it to restore after a slight interval. Relay 904 thereafter remains operated and relay 903 remains restored until relay 902 is again permitted to restore. At the upper contacts of relay 903, a circuit is closed for release relay 914, with the result that relays 914-916 operate successively and subsequently restore successively when the clear out relay 903 falls back. By the interaction of these relays, an impulse is transmitted as hereinbefore explained over the forced-release conductor 954 to cause a relay such as the forced release relay 708 of the local connector LOC to operate and clear out the link being held. The calling subscriber may replace his receiver and again remove it to initiate a new call which will then be handled over the remaining operating trunk.

Returning an operating trunk to service

20 The operating trunk OT1 at the common-equipment unit CE1 may be returned to service upon the dialling of the number 82, whereupon the C wiper of the connector in use will contact the C terminal 82, Fig. 9, part 1, or a multiple 25 thereof, thereby extending ground potential to the junction of the lower winding of make-busy relay 902 and the associated resistor. This ground potential shunts the current away from the lower winding of relay 902 and permits the 30 relay to restore and open its locking circuit. Relay 904 is thereupon permitted to restore, as is the seizing control relay 901.

The common equipment unit CE2 and the associated operating trunk OT2 are removed from 35 service by the dialling of the make-busy number 83 and are returned to service upon the dialling of the remove-busy number 84. This is controlled through the illustrated terminals 83 and 84, or multiples thereof.

40 *Completing a local-service call from Mount Morris to Leicester*

The way in which local service connections are set up from Mount Morris lines to lines terminating in the Leicester exchange will now be pointed out. Assuming that a call is received at the manual switchboard in the Mount Morris exchange from a local subscriber who desires a connection with a subscriber at the Leicester exchange, the 45 operator may insert the calling plug (not shown) of her cord circuit into the jack J1, Fig. 11. Sleeve relay 1101 is operated over the sleeve terminal of the jack J1 to disconnect the upper winding of ring-up relay 1102. No supervisory 50 bridge exists across the tip and ring conductors of the jack J1, as the manual switchboard in the Mount Morris exchange is assumed to be a magneto switchboard, serving local-battery lines.

At its upper contacts, sleeve relay 1101 bridges 55 the polarized supervisory relay 1105 across the condenser associated with the right-hand windings of repeating coil 1100, thereby closing a calling bridge across the local service trunk LST. The supervisory relay 1105 is not operated at this 60 time because of the direction in which the current flows through its windings. The line circuit LC3, Fig. 5, is similar to the line circuit LC1; therefore, a finder such as the finder F1, Fig. 6, is now started and is caused to make connection with the 65 local-service trunk LST by way of terminals 551 or multiples thereof. The call originated over the local service trunk LST is handled at the remotely operated exchange in the same way that a call originated over a local subscriber line is 70 handled; a control operator at Mount Morris is 75

signalled over one of the two operating trunks OT1 and OT2 to take the number and control the setting up of the connection in the Leicester exchange.

The established connection is broken down 5 when the Mount Morris operator removes the plug from the jack J1, permitting sleeve relay 1101 to restore and remove the bridge across the inter-exchange conductors of the local service trunk LST. 10

Calls from Leicester to Mount Morris

As previously mentioned, the local service trunk LST, Figs. 5 and 11, is one of four local service trunks assigned to the handling of calls between 15 the Mount Morris and Leicester exchanges. In the Leicester exchange, these four local service trunks are accessible from adjacent sets of contacts located in the same level of the connector banks. The number assigned to this trunk group 20 includes the two digits necessary to raise the connector wipers opposite the desired level and to rotate them into engagement with the first trunk of the group, assumed to be the trunk LST. Terminals 550 are these terminals in the bank 25 of one of the connectors. In addition, the trunk-group number contains a digit (such as the digit 2) which is to be dialled in order to cause the setting of a party selector such as the party selector PS1, Fig. 7, part 2, into a position to cause ringing 30 current to be applied to signal the Mount Morris operator.

In the event that the first trunk of the group is idle, the call is put through in the same way as a call to a local line. On the other hand, if 35 the first trunk is busy, a busy signal is transmitted to the control operator and to the calling subscriber from the common-equipment unit in use, and the control operator is expected to dial an additional digit 1 in order to cause the wipers 40 of the connector to advance to the next trunk of the group, and if this next trunk is busy the operator repeats the dialling of the additional digit 1, and she may cause the wipers to be advanced from one trunk to the next until all have 45 been tested. As soon as an idle trunk is reached, the busy tone signal is removed and connection is made with the trunk. The circuit arrangements involved in bringing about the additional 50 advance of the wipers of the connector when the first trunk of the group is busy have been described hereinbefore in connection with giving multi-line service to subscribers of the Leicester exchange.

The supervisory operations involved in the extension of calls over the local-service trunks from 55 Leicester to Mount Morris are covered in detail hereinafter in the description of paystation calls.

Handling calls from paystation lines

As explained hereinbefore in connection with the trunking diagram, Fig. 2, paystation lines of the Leicester exchange are given outgoing service directly to the Mount Morris exchange by way 60 of local service trunks, such as the local service 65 trunk LST. One paystation line, PSL, is illustrated in Fig. 2. It extends from the paystation 1600 to the paystation line circuit LC4, whose lineswitch LS has access to the local-service trunk LST and to the other local-service trunks extending 70 between the Mount Morris and Leicester exchanges. The line circuit LC4, together with the associated lineswitch LS is shown in circuit diagram in Fig. 16.

Referring now particularly to Fig. 16, the op- 75

erations involved when a subscriber at paystation 600 on the line PSL initiates a call will be described.

Upon the removal of the receiver at paystation 5 1600, line relay 1602 operates through contacts of cut-off relay 1601 and closes a circuit at its lower contacts, through contacts of ring-cut-off relay 1606, for relay 1608 of the timer comprising relays 1608 and 1609. By this operation the timer 10 is started for the purpose of sounding an alarm over the common-alarm conductor 1611 in the event that the lineswitch is unable to find an idle trunk within the time for which the timer 1608—1609 is set. At this point it may be explained that 15 in the event that switching relay 1604—1606 fails to operate, responsive to the finding of an idle trunk, for a period of from one to three seconds (depending upon the adjustment of relays 1608 and 1609), upon the operation of relay 1609 an 20 alarm is given over conductor 1611.

Relay 1608 has a weighted contact as shown, which contact is struck by the armature and caused to vibrate for an interval. During the vibration of relay 1608, relay 1609 is unable to operate. 25 When the vibration has substantially ceased, however, relay 1609 operates and locks itself through contacts of release relay 1603 and closes an alarm circuit over conductor 1611 through contacts of switching relay 1604. In addition, relay 1609 disconnects operating magnet 1610 at its inner upper armature, while at its middle upper armature it connects the busy-tone conductor 1612 through contacts of relay 1604 to the calling line to inform the calling subscriber 30 of the busy condition. This connection is made through a small individual, current-limiting condenser, as shown.

Assuming now that the lineswitch LS is able to find an idle trunk, the trunk hunting operation 40 is completed in a very short time, and before the timer 1608—1609 has had time to function as above pointed out. This trunk hunting operation is performed as follows:

Line relay 1602 operates release relay 1603 45 through its inner contacts. Relay 1603 places ground potential on the generator-start lead 1617; closes a hunting circuit for operating magnet 1619 through contacts of timer relay 1609, the inner upper contacts of relay 1603, and contacts of switching relay 1604, to enable the switch LS to hunt for an idle trunk in the event that the one upon which the wipers 1651 are standing is in use; it closes a circuit for switching relay 1604 in series with operating magnet 1610, to 50 become effective when an idle trunk is found; and at its upper armature it disconnects cut-off relay 1601 and connects the associated C lead to ground so as to guard the paystation line against seizure at terminals 1650 or the multiples thereof.

When the lineswitch LS finds an idle local service trunk, the local service trunk LST, Fig. 5, for example, no further operation of magnet 1610 takes place, and switching relay 1604 operates in series with magnet 1610. Upon operating, switching relay 1604 disconnects the alarm conductor 1611 so as to prevent an alarm from being subsequently given; it shunts the inner upper contacts of timer relay 1609 at its own inner upper contacts so as to avoid interruption in its own 60 circuit when relay 1609 operates; it opens the previously existing test circuit for magnet 1610 and applies guarding ground potential directly to C wiper 1651; it takes over the guarding work of the upper armature of release relay 1603; and 65 it extends the talking conductors of the line PLS

through talking condensers 1615 and 1616 to the negative and positive wipers 1651, at the same time opening an additional point in the incomplete circuit path for applying busy-tone current from conductor 612.

The application of ground potential to the C wiper 1651 results in the extension of ground potential over the associated C conductor to the cut-off relay of the line circuit LC3, Fig. 5, corresponding to cut-off relay 302 of the line circuit 10 LC1, Fig. 3. This cut-off relay operates to clear the trunk LST at the line circuit LC3.

As a further result of its energization, switching relay 1604 completes a circuit previously prepared at the middle armature of line relay 1602 15 through contacts of ring-cut-off relay 1606 for ringing relay 1605. Relay 1605 thereupon operates to transfer the negative wiper 1651 to the common ringing lead 1615 for the purpose of transmitting ringing current over the local-service 20 trunk LTS to the Mount Morris exchange, a return path to ground being provided through the middle armature of relay 1605 and the positive wiper 1651. At the same time, ringing relay 1605 extends the common ringing lead 1614 through 25 the condenser 1618 and resistor 1619 to ground through the upper winding of ring-cut-off relay 1606. Keeping in mind that the lead 1614 is one to which ringing current is applied directly by the usual ringing machine, it will be seen that 30 ring-cut-off relay 1606 will operate only after the ringing machine or generator has come into operation, which it is caused to do by the above-mentioned application of ground potential to the generator-start lead 1617. The ring-cut-off relay 1606 therefore acts as an automatic delay device to enable the ringing machine to become 35 started before it breaks the circuit of ringing relay 1605.

When ring-cut-off relay 1606 operates, it closes 40 a locking circuit for its lower winding and breaks the circuit of slow-releasing ringing relay 1605, permitting this relay to restore after a slight interval and thereby terminate the ringing operation. The application of ringing current given 45 in this way may be described as a "splash ring".

Ring-cut-off relay 1606 also opens the circuit of timer relay 1608, which occurs under normal conditions before relay 1609 has had time to operate; it connects up back-bridge relay 1607 so that 50 it can respond when the operator answers; and it connects the paystation-tone lead 1613 through the associated individual, current-limiting condenser to the negative wiper 1651, by way of contacts of timer relay 1609. The tone applied 55 from lead 1613 is a characteristic tone used to inform the operator that a paystation line is calling. This tone continues to be applied until the operator responds, and for a short time thereafter, as will be pointed out subsequently.

In the Mount Morris exchange, the application of ringing current made as above pointed out results in the operation of the ring-up relay 1102, Fig. 11, by induced current transmitted through the windings of repeating coil 1100. Relay 1102 65 closes a locking circuit for its lower winding at its inner contacts, while at its lower contacts it closes a circuit for call lamp 1121.

When the Mount Morris operator responds to the lighted condition of the call lamp 1121 (by 70 inserting the answering plug of a cord circuit into the jack J1), and sleeve relay 1101 responds and connects supervisory relay 1105 in circuit, relay 1105 operates because of the fact that the talking conductors are reversed at the negative and posi- 75

tive connector terminals 550 and the multiples thereof, causing current to flow through the supervisory relay in a direction opposite to that in which it flows through this relay when a call is originated over the trunk LST at the Mount Morris exchange. Upon operating, relay 1105 closes a circuit for clear-out relay 1104, and relay 1104 closes an operating circuit for auxiliary relay 1103. The operation of relays 1103 and 1104 is for the purpose of giving a disconnect signal to the operator subsequently, as will be explained later.

In the Leicester exchange, back-bridge relay 1607 responds when the operator answers and causes the supervisory relay 1105 to be connected in circuit. Relay 1607 closes a circuit for timer relay 1608. The paystation signal being applied to the talking circuit from common lead 1613 is now heard by the Mount Morris operator, in addition to being heard by the calling subscriber. This tone continues to be heard until relays 1608 and 1609 operate successively.

Relay 1609 disconnects tone conductor 1613 when it operates, whereupon conversation may proceed between the calling paystation subscriber and the Mount Morris operator.

The Mount Morris operator may extend the paystation call as desired.

It is assumed that the paystation 1600 is equipped with a coin-deposit box of the usual type, separate coin chutes being provided for coins of different denominations, each channel being provided with a characteristic gong or other sounding device which emits a sound of sufficient intensity upon the dropping of a coin in the deposit box that the operator is notified through the transmitter at the paystation.

When the paystation subscriber replaces his receiver upon the termination of the conversation, line relay 1602 restores and thereby brings about the restoration of relays 1603 to 1609, clearing out the line circuit. The disconnection of back-bridge relay 1607 upon the restoration of ring-cut-off relay 1606 results in the restoration of the polarized supervisory relay 1105 in the Mount Morris exchange.

Relay 1105 permits relays 1104 and 1103 to restore successively. During the interval required for the slow-releasing relay 1103 to restore, the two poles of the exchange battery are connected by way of the left-hand windings of the repeating coil 1100 to the top and ring conductors of the jack J1 so as to furnish actuating current to the ring-off supervisory signal assumed to be located in the cord circuit in use.

When the operator removes the plug of the cord circuit from the jack J1, the restoration of sleeve relay 1101 results in the opening of the control bridge across the line LST through the supervisory relay 1105.

Operating the Leicester exchange from Geneseo

It has been pointed out hereinbefore that provisions are made for operating the remotely controlled Leicester exchange from the Geneseo exchange during a time when neither of the operating trunks OT1 and OT2 is serviceable. It has been pointed out moreover that it is advantageous to employ a pair of conductors as an alternative 70 operating trunk which does not extend along the same physical route as the conductors of the operating trunks, as there is then less likelihood of the alternative conductors being unserviceable at the same time that the operating trunks are 75 out of order.

In order to effect the transfer of the control point, an operator in either the Mount Morris exchange or in the Geneseo exchange may dial the transfer number 85 into any connector of the Leicester exchange. When the number 85 is 5 dialled, the C wiper of the connector in use is brought into engagement with the C terminal 85, Fig. 8, or a multiple thereof, closing a circuit for the upper winding of transfer relay 856. Upon operating, transfer relay 856 closes a locking circuit for itself by way of the resistor 857. At its lower armature, relay 856 grounds the No. 2 switching conductor 944', thereby actuating the seizing-control relay in the common-equipment unit CE2, corresponding to seizing-control relay 15 901 in the common-equipment unit CE1. In addition, transfer relay 856 disconnects the outgoing talking conductors associated with the common-equipment unit CE1 from the conductors of operating trunk OT1 and transfers them 20 to the outgoing conductors 1427 and 1428 of the toll line TL2, Figs. 14 and 12. At the same time, relay 856 connects a substitute current-supply bridge to the conductors of the holding trunk OT1 so as to enable the operating trunk to be 25 tested more readily and to enable line relay 1003 to become operated over the operating trunk when the necessary repair has been effected.

Additionally, transfer relay 856 disconnects conductors 1424 and 1425 from the toll-line conductors 1427 and 1428 so as to leave the toll line free at the Leicester exchange for the performance of the control, operation, while at its uppermost armature it places ground potential on conductor 1426 so as to guard the disconnected local end of the toll line TL2 from seizure by the connectors in the Leicester exchange.

In order to complete the transfer at the Geneseo exchange, the transfer key K3 is operated so as to shift the conductors of the toll line 40 TL2 from the usual terminating equipment shown in Fig. 12 to the control equipment of Fig. 13, which is like the control equipment illustrated in Fig. 10.

When operation of the remotely controlled 45 Leicester exchange is to be resumed from the Mount Morris exchange, transfer relay 856 is restored responsive to the dialling of the restoring number, 86, on any of the connectors in the Leicester exchange. By this operation, the C 50 wiper of the connector in use places ground potential on the C terminal 86, Fig. 8, or a multiple thereof, extending ground potential to the junction of the lower winding of transfer relay 856 and the associated resistor 851 and thereby 55 short circuiting the lower winding of the relay. The relay thereupon restores and dissociates the common equipment unit CE1 from the toll line TL2 of Fig. 14, again placing the common equipment unit CE1 under the control of the operating trunk OT1 extending to the Mount Morris exchange, and permitting the seizing-control relay of the common equipment unit CE2 (corresponding to relay 901 of CE1) to restore so 60 as to permit calls to be handled through the common-equipment unit CE2.

A call from Leicester to Geneseo

The operations involved in extending a connection from a calling line in the Leicester exchange to the toll switchboard in the Geneseo exchange, Fig. 12, will now be explained. For this purpose it may be assumed that the subscriber at substation 300 has removed his receiver; that, as the result, the finder-connector 70

link of Figs. 6 and 7 has made contact with the calling line; and that the common equipment unit CE1 of Fig. 9 has been taken for use to cause the control operator in the Mount Morris exchange to be signalled over the operating trunk OTC.

The toll lines extending from Leicester to Geneseo are accessible to connectors in the Leicester exchange by way of the tenth level, the first of these lines being reached when the number 01 is dialled. Accordingly, the first digit dialled by the control operator is the digit 0, resulting in ten impulses being delivered over vertical conductor 956 and through contacts of the operated connecting relay 703 to vertical magnet 716 of the local connector LOC. At this time, the wipers 700 are raised opposite the tenth level of bank contacts. The O-level springs 721, 723, and 724 are thereupon shifted to alternate position. O-level springs 723 prepares a circuit for the upper winding of switch-through relay 705 over pilot conductor 759; springs 721 prepares a circuit for the lower winding of ring-cut-off relay 710; and O-level springs 724 disconnects pick-up relay 711 so as to avoid an operation of this relay.

In the common-equipment-unit CE1, the tens-digit relays 922 and 923 are operated as hereinbefore described, and relay 923 transfers the common impulse conductor 934 from vertical conductor 956 to rotary conductor 957.

When the second digit, the digit 1, is dialled, the single resulting impulse is transmitted over rotary conductor 957 to rotary magnet 717. The wipers 700 are thereupon driven into engagement with the first set of bank contacts in the tenth level, assumed to be contact set 1450, Fig. 15, of multiples thereof, associated with the outgoing trunk-circuit OTC. If the trunk line TL2 associated with this first set of bank contacts is in use, there is a ground potential on the C terminal in this set. In this event, busy-test relay 917 becomes operated and prepares a locking circuit for itself which is closed upon the restoration. In this event, a busy tone signal is applied at the upper contacts of relay 917 to inform the calling operator of the busy condition.

For the sake of uniformity in the numbering system, an additional digit, such as the digit 2, is assigned to the group of Geneseo toll-trunks. When this digit is dialled, the resulting two impulses delivered over common impulse conductor 934 pass through contacts of the operated tens digit relay 923, through contacts of the operated units digit relay 924 (the lower winding of relay 924 is now energized in multiple with the lower winding of busy test relay 917), through contacts of relays 926 and 928, and over the party-selector-operating conductor 958 to operating magnet 743 in the party selector SPI. The wipers of the party selector are thereupon set upon the second associated set of bank contacts, but the setting of the party selector is only incidental at this time.

The first party-digit counting relays 925 and 926 are operated successively under the control of series auxiliary relay 919, and relay 926 disconnects the lower winding of units-digit relay 924, as code-group pilot relay 920 is not operated at this time. Relay 924 thereupon restores and again transfers conductor 934 to the rotary conductor 957 so as to permit a further advance of the wipers 700 of the connector LOC under the control of rotary magnet 717.

The operator may now dial the digit 1 one or

more additional times in order to cause the wiper 700 to advance until the last toll line of the group is reached or until an idle toll line is reached. When an idle toll line is reached, busy-test relay 917 restores, and the lower winding of idle-test relay 924 is energized over the test lead 960 and through the C wiper 700 in series with the winding of the relay connected to the C lead of the called toll line. Relay 921 locks its upper winding to conductor 935, whereupon the upper winding of units-digit relay 924 is energized in multiple with the upper winding of relay 921. The common impulse conductor 934 is thereby disconnected from rotary conductor 957, but it is not again connected to party selector operating conductor 958 because conductor 958 is now disconnected at the upper contacts of relay 926. At the same time, toll-cut-in relay 929 is operated in multiple with the upper windings of relays 921 and 926, through contacts of relay 926; responsive to the operation of relay 921 in closing a locking circuit for its upper winding. The operation of toll-cut-in relay 929 results in the operation of switch-through relay 705 as will be pointed out subsequently.

The operations occurring when the first toll line of the group is busy having been explained, it will now be assumed that the first toll line of the group (toll line TL2, Fig. 14) is idle when the wipers 700 of the connector LOC land upon contacts 1450 responsive to the dialing of the number 01. In this event, idle-test relay 921 operates immediately following the cessation of the second digit 1, its circuit including its own lower winding and test lead 960, contacts of the operated connecting relay 703, contacts of busy relay 704, C wiper 700, C terminal 1450, C lead 1421, contacts of relay 1405 and the upper winding of local relay 1406. Local relay 1406 operates in this circuit to disconnect C conductor 1423 from the lower winding of toll relay 1405 and to connect it to ground, so as to immediately guard the terminals 1451 and the multiples thereof in the banks of the toll connectors.

The placing of ground potential on the C terminal 1450 results in the previously mentioned energization of the upper winding of local relay 1406 over conductor 1421 to ground the conductor 1423 and thereby guard terminals 1451. The ground potential on conductor 1421 is extended through the upper contacts of local relay 1406 to transfer relay 1411, causing this transfer relay to become operated and thereby shift the conductors 1424 and 1425 of the toll line TL2 from the toll connector TC2, Fig. 15, through contacts of splash-ring relay 1409 to the windings of repeating coil 1400. Transfer relay 1411 also closes a circuit through contacts of ring-cut-off relay 1410 for splash-ring relay 1409. Ring-cut-off relay 1409 operates and closes a circuit for relay 1410, with the result that relay 1410 operates and locks itself to the contacts of transfer relay 1411, at the same time opening the circuit of the slow-releasing splash-ring relay 1409, and permitting this relay to restore. Splash-ring relay 1409 is therefore operated only momentarily to project ringing current over conductors 1424 and 1425 and the extended conductors 1427 and 1428 of the toll line TL2, to signal the Geneseo operator.

It is to be noted that the exchange generator 70 is maintained in operation at this time because relay 914 is maintaining generator-start lead 948 grounded.

In the common equipment unit CE1, the operation of idle-test relay 921 results in the oper- 75

ation of units-digit relay 924, and the dialling circuit is extended to conductor 958, over which the two impulses of the party-selecting digit 2 are transmitted when this digit is dialled.

- 5 At the end of the dialling of the party-selecting digit (added to the number for the sake of uniformity) relay 926 operates under the control of relay 925, controlled in turn by series auxiliary relay 919. Upon operating, relay 926 completes 10 a circuit for toll-cut-in relay 929 in multiple with the upper winding of relays 921 and 924. Upon operating, relay 929 applies a negative potential from the ungrounded negative pole of the exchange battery through the associated resistor 15 to pilot conductor 959. By this operation, a circuit is closed over conductor 959, through contacts of the operated connecting relay 703, the shifted 0-level springs 723, and the upper winding of switch-through relay 705 to ground. Relay 705 is not previously operated over conductor 20 759 because conductor 759 normally extends ground through the upper winding of code-group-pilot relay 920 and contacts of series relay 918.
- 25 When it operates as above pointed out, switch-through relay 705 connects the forced-release relay 708 to the EC wiper 700; it closes an additional circuit for release relay 707 so as to maintain this relay energized independent of line relay 30 706; and it disconnects the incoming talking conductors 621 and 622 from the windings of line relay 706 and extends them directly to the negative and positive wipers 700, so as to enable the line relay of the seized toll line to be held directly 35 over the calling line. In addition, relay 705 prepares a locking circuit for its lower winding at its lower contacts which becomes closed subsequently upon the operation of cut-off relay 702.

- When the operator clears out the operating 40 trunk OT1 and the common-equipment unit CE2, the application of ground potential through contacts of the actuated idle-test relay 921 to cut-off lead 955 results in the operation of cut-off relay 702 through contacts of connecting relay 45 703. In addition to locking itself to the grounded holding conductor 623 in multiple with the winding of selecting relay 701, and disconnecting the winding of connecting relay 703, and applying ground potential directly to the C wiper 700, cut-off relay 702 completes the locking circuit of the 50 lower winding of relay 705, which locking circuit extends from the grounded conductor 734 through contacts of ring-cut-off relay 710, contacts of busy relay 704, contacts of the now-operated cut-off relay 702, the O-level contacts 721, and thence through the No. 70 contacts 722 to the lower winding of relay 705. A branch of this circuit extends through the lower winding of the operated relay 705 to the lower winding of ring-cut-off relay 710. 55 Relay 710 thereupon operates and locks itself directly to the grounded conductor 734, thereby closing a multiple locking circuit for the lower winding of relay 705 through the lower contacts of the latter relay. Ring-cut-off relay 710 also 60 disconnects ground potential from interrupter-start lead 736 so as to avoid an unnecessary operation of the ringing interrupter.

- Because of the switching-through operation performed at the two uppermost armatures of 70 the switch-through relay 705 of the local connector LOC, line relay 1402 of the outgoing trunk circuit OTC2 is now operated over the calling line through conductors 1419 and 1420 and left-hand winding of repeating coil 1400. Front-release-relay 75 1401 responds to the operation of line relay

1402 to prepare a forced-release circuit over the forced-release EC lead 1422, which becomes effective in case the Geneseo operator does not respond and the calling subscriber replaces his receiver without a response having occurred. 5

In the Geneseo exchange, Fig. 12, the momentary application of ringing current brought about by the momentary operation of relay 1409, as previously explained, results in the operation of the sensitive ring-up relay 1204. Relay 1204 locks 10 its lower winding to ground at contacts of relay 1203 and energizes call relay 1205 to light the call lamp 1206.

When the operator responds to the lighted condition of the call lamp 1206 by inserting the plug 15 of an idle cord circuit into the jack J2, sleeve relay 1202 is energized through the sleeve of the jack J2 to complete a circuit for the lower winding of line relay 1201. Relay 1201 thereupon closes a circuit for the lower winding of cut-off relay 20 1203. Cut-off relay 1203 opens the locking circuit of relay 1204; opens the bridge circuit through the upper winding of relay 1204; and it disconnects sleeve relay 1202 and prepares a locking circuit for itself to the sleeve of the jack J2 which 25 is closed as soon as the sleeve relay restores. Sleeve relay 1202, upon restoring, opens the circuit of the lower winding of line relay 1201, but relay 1201 remains operated through its upper winding and over the tip and ring contacts of the 30 jack J2.

At its upper contacts, cut-off relay 1202 places a shunt around the condenser associated with the left-hand windings of repeating coil 1200, thereby bringing about a flow of direct current 35 over the toll line TL2 from the windings of back-bridge relay 1408, in series with the differential windings of recall relay 1407 and the right-hand windings of relay 1400. Back bridge relay 1408 is energized in this circuit, but the differential 40 recall relay 1407 does not operate. Back-bridge relay 1408 prepares a special self-locking circuit for itself at its upper contacts; it operates back-release relay 1400 at its lower contacts; while at 45 its inner lower armature it opens a point in the forced-release circuit and closes a circuit through contacts of recall relay 1407 for supervisory relay 1404. Supervisory relay 1404 now operates and closes its contacts, but no effect is produced because change-over relay 1403 is not operated at 50 this time.

The toll operator in the Geneseo exchange may now complete the call as desired.

Recalling the Geneseo operator

With back-bridge relay 1408 holding back release relay 1400 operated, the restoration of line relay 1402 does not result in the application of ground potential to forced-release relay 1422. Consequently, the calling subscriber may recall 60 the operator by a depression of his receiver hook without causing the local connector LOC, Fig. 7, to release. When line relay 1402 restores, and pending the resultant restoration of release relay 1401, a circuit is closed through contacts of back-bridge relay 1408 and contacts of relays 1401 and 1402 for reoperating splash-ring relay 1409 momentarily. Relay 1409 projects ringing current over the toll line TL2 to recall the Geneseo operator. It is to be noted that relay 1409 completes 65 a locking circuit for the upper winding of back-bridge relay 1408 so as to avoid a restoration of relay 1408 during the momentary application of ringing current. Line relay 1402 and front-release relay 1401 reoperate when the switchhook 70 75

contacts are permitted to reclose at the calling substation.

Clearing out the toll connection

5 When the calling subscriber replaces his receiver at the end of the conversation relays 1402 and 1401 restore, and splash-ring relay 1409 is operated momentarily as previously pointed out, this time to give the Geneseo operator a disconnect signal.

When the Geneseo operator removes the plug of her cord circuit from the jack J2, relays 1201 and 1203 restore, and relay 1203 opens the bridge across the toll line TL2, permitting back-bridge relay 1408 in the outgoing trunk circuit OTC2 to restore. Upon restoring, back-bridge relay 1408 opens the circuit of back-release relay 1400 and it closes a forced-release circuit through contacts of relay 1400 for the length of time required for this relay to restore after its circuit is opened. This forced-release circuit extends over the EC conductor 1422, through the EC wiper 700, and by way of contacts of switch-through relay 705 to the forced-release relay 703. Relay 703 operates responsive to this momentary impulse of current. Being a slow-acting relay, it remains operated sufficiently long to permit the locked-up relays in the connector LOC and the finder F1, Fig. 6 to restore. The finder and the connector are restored to normal position by their release magnets as a result. In the trunk circuit OTC2, Fig. 14, when the local connector removes ground potential from conductor 142, relays 1406, 1411, 1410, and 1409 restore. It is to be noted particularly that the local connection is automatically cleared out when the operator takes down the connection whether line and release relays 1402 and 1401 have restored or not. Therefore, a defective local line cannot withhold a toll line from service.

Toll call from Mount Morris to Geneseo by way of Leicester

Upon referring to Figs. 1 and 2, it will be seen that a toll operator at Mount Morris may set up a toll connection to a subscriber at the Leicester exchange by way of the toll line TL1, using the toll connection TC1, Fig. 2. It will be seen further that the toll connector TC2 may be used to extend a connection through the Leicester exchange to the Geneseo exchange by way of the toll line such as the toll line TL2. In order to explain the features of the outgoing trunk circuit OTC, Fig. 14, more fully, it will now be assumed that the Mount Morris operator has taken the toll line TL1, Figs. 1 and 2, for use and has dialled the designation of the trunk group extending from the Leicester exchange to the Geneseo exchange. It will be assumed further that the toll line TL2 is idle, and that the toll connector TC2, Fig. 2, accordingly seizes the toll line TL2 by way of the outgoing trunk circuit OTC2, Fig. 14, at the toll terminals 1451.

When terminals 1451 are seized and ground potential is applied to C conductor 1423, the lower winding of toll relay 1405 is energized through contacts of local relay 1406. Toll relay 1405 places ground potential on C conductor 1421 to guard the trunk from seizure by way of the local connectors. It also operates change-over relay 1403 to disconnect the windings of line relay 1402 and to prepare a supervisory bridge across conductors 1419 and 1420, through contacts of the supervisory relay 1404. In addition, change-over relay 1403 operates transfer relay 1411, which in

turn operates splash-ring relay 1409 and ring-cut-off relay 1410, as previously described, to cause ringing current to be momentarily projected over the toll line TL2 to signal the Geneseo operator.

When the Geneseo operator responds, back-bridge relay 1408 is operated as previously described. At this time, when supervisory relay 1404 responds to the operation of back-bridge relay 1408, it closes a bridge across the conductors 1419 and 1420 by way of contacts of the actuated change-over relay 1403, thereby operating the back-bridge relay in the toll connector TC1, Fig. 2, corresponding to back-bridge relay 1506 of the toll connector TC2, Fig. 15, to thereby operate 15 the associated back-release relay similar to 1505 to prepare for an operation of the recall ringing relay similar to 1501.

Recalling the calling toll operator

Assuming now that the Geneseo toll operator desires to recall the Mount Morris toll operator, she momentarily operates the recall key K4, Fig. 12, momentarily operating the recall relay 1407. Back-bridge relay 1408 remains operated, but supervisory relay 1404 is restored to momentarily open the supervisory bridge across conductors 1419 and 1420, thereby bringing about a momentary operation of the recall relay in the toll connector TC1 which corresponds to the recall relay 1501 of the toll connector TC2, Fig. 15. The recall relay momentarily projects ringing current back over the toll line TL1, Figs. 2 and 1, to recall the Mount Morris toll operator.

When the connection is to be cleared out, the toll connector TC1 restores responsive to the opening of the toll line TL1 in the Mount Morris exchange.

When the outgoing trunk circuit OTC, Fig. 14, is freed at the terminals 1451, relays 1405 and 1403 restore, and relay 1403 permits relays 1411, 1410, and 1409 to restore.

Toll call from Geneseo to Leicester

When the Geneseo toll operator receives a toll call to be extended to a line in the Leicester exchange, she may complete this call over one of the Geneseo-to-Leicester toll lines, the toll line TL2, for example. When the operator inserts the plug of a cord circuit into the jack J2, Fig. 12, to take the toll line TL2 for use, sleeve relay 1202 operates and disconnects the upper winding of cut-off relay 1203.

When the plug has been fully inserted into the jack, line relay 1201 operates over the tip and ring contacts of the jack and closes a temporary locking circuit for its lower winding through contacts of sleeve relay 1202, and it closes a circuit for the lower winding of relay 1203. Cut-off relay 1203 thereupon operates and prepares to lock itself to the sleeve of the jack J2 as soon as the slow-acting sleeve relay 1202 restores responsive to being disconnected by the cut-off relay.

At its upper contacts, cut-off relay 1203 closes a control circuit over the toll line TL2 by way of the left-hand windings of repeating coil 1200, which circuit extends over conductors 1416 and 1417, and through the right-hand windings of repeating coil 1550 to the windings of line relay 1502 of the toll connector TC2. Line relay 1502 brings about the operation of release relay 1503. The upper winding of vertical-series relay 1504 is energized through off-normal contacts 1527. Vertical-series relay 1504 prepares an operating circuit for vertical magnet 1528 and a holding

circuit for its lower winding, and it shifts the circuit of the lower winding of line relay 1502 so that it includes the dial tone lead 1626, whereby a distinctive dial-tone signal is transmitted 5 back through the windings of line relay 1502 to the calling Geneseo operator to inform her that the toll line is in working order and that she may now dial the desired number.

- It is to be observed that the equipment layout 10 in Fig. 12 is made under the assumption that two toll positions are provided in the Geneseo exchange through which calls may be extended over the toll line TL2. The dial key K5 is so located that it may be reached from either position. This 15 key may be thrown to the left to associate the dial 1301 of position 1 with the toll line TL2, and it may be actuated to the right to associate the dial 1302 of position 2 with the control equipment.
- 20 The dial key K5 is now actuated in the proper direction to associate the dial of the calling toll operator with the toll line TL2, following which the operator dials the digits in the desired number and then restores the dial key K5.
- 25 When the first digit is dialled, line relay 1502 is momentarily deenergized a corresponding number of times. Each time it restores, line relay 1502 closes a circuit through contacts of the actuated slow-acting release relay 1503 and through 30 contacts of the actuated vertical-series relay 1504 for vertical magnet 1528. By the operation of the vertical magnet, the wipers 1509 are raised step-by-step until they come to rest opposite the desired level of bank contacts. Off-normal contacts 35 1527 open the initial circuit of the upper winding of vertical-series relay 1504, but the lower winding of this relay is connected in multiple relationship with the winding of vertical magnet 1528, with the result that relay 1504 remains 40 operated throughout the series of impulses and restores at the end of the series to transfer the impulse circuit from vertical magnet 1528 to rotary magnet 1529. At the same time, the restoration of vertical-series relay 1504 shifts the circuit of 45 the lower winding of line relay 1502 back to ground, disconnecting the dial-tone conductor 1525.

When the second digit is dialled, the resulting 50 impulses are delivered through contacts of switching relay 1511 to rotary magnet 1529. By the operation of magnet 1529, the wipers 1500 are rotated over the contacts of the selected level until they come into engagement with the terminals of the desired line. Rotary-series relay 1509 55 operates in multiple with rotary magnet 1529 upon the delivery of the first impulse. Being slow-releasing, this relay remains actuated throughout the rotary series of impulses. At its inner armature relay 1509 operates series-auxiliary relay 1510, while at its upper armature, it disconnects the C wiper 1509 from the test winding of switching relay 1511 and transfers it to the winding of busy relay 1508. As a result, if the called line is busy, relay 1508 operates and 60 prepares a locking circuit for itself, and prepares a busy-tone connection. Then, when rotary series relay 1509 restores, rotary magnet 1529 is disconnected. At the same time, rotary series relay 1509 completes the locking circuit of busy 65 relay 1508 to the grounded conductor 1418 (grounded via upper contacts of release relay 1503). This locking circuit includes contacts of switching relay 1511. Upon the restoration of series-auxiliary relay 1510, a connection is completed from the busy-tone lead 1521 to the upper 70 75

talking conductor, whereby a busy-tone signal is transmitted to the calling operator to inform her of the busy condition of the called line.

In the event that the station being called is provided with multi-line service as hereinbefore 5 discussed, the operator may now dial the additional digit 1 to cause a further advance of the wipers 1500 to the next line. On the other hand, if the call is to an individual line the operator removes the plug from the jack J2, Fig. 12, and 10 permits the partially established connection to be cleared out.

Assuming now that the called line is idle, busy relay 1508 is not operated when the wipers 1500 come to rest. In this case, the C wiper 1500 encounters a negative potential on the C terminal of the called line, closing a circuit through contacts of rotary-series relay 1509 for the testing winding of switching relay 1511, which circuit 15 extends, to ground, through contacts of busy relay 1508, to the grounded conductor 1418.

Upon operating, switching relay 1511 locks itself to conductor 1418; transfers the impulse conductor from rotary magnet 1529 to operating magnet 1533 of the party selector PS2; prepares 25 a circuit for pick-up relay 1512; disconnects busy relay 1508 from the test circuit; opens a point 30 in the busy-signalling circuit path at its upper contacts; and it connects up the negative and positive wipers 1500 to prepare for the ringing 30 operation.

In the event that the line being called is one having a single-digit code-designation (a code digit having a value from 2 to 6), the next digit dialled is the final digit. The positioning of 35 wipers 1531 and 1532 takes place responsive to the operation of magnet 1532 through contacts of the operated switching relay 1511. Wiper 1531 prepares a ringing circuit from the encountered one of the associated coded generator leads 40 1533. In this event, the code-group switching relay 1515 is not operated.

Off-normal contacts 1535 being now closed, upon the restoration of series-auxiliary relay 1510 when rotary-series relay 1509 restores at 45 the end of the party selecting digit, busy relay 1508 is reoperated to prepare a circuit for release magnet 1534; to place ground potential on interrupter-start conductor 1523 through contacts of ring-cut-off relay 1507; and to extend the 50 common pick-up lead 1523, through contacts of the operated switching relay 1511, to pick-up relay 1512. Pick-up relay 1512 operates when the pick-up impulse is received and locks itself to conductor 1418, at the same time opening its 55 initial circuit.

At its upper contacts, pick-up relay 1512 completes the ringing circuit from the contacts bridged by wipers 1531, through the upper winding of ring-cut-off relay 1507, to the negative conductor of the called line, through contacts of relays 1516, 1517, 1507, and 1511. The return circuit for the ringing current is to ground by way of the positive wiper 1500 and contacts of 60 relays 1511, 1507, and 1517.

On the other hand, if the line being called is a line signalled with a two-digit code, two party digits are dialled. The first party digit is the digit 1. In this case wipers 1531 and 1532 are 70 advanced only a single step. Then when rotary series relay 1509 restores after having been operated responsive to the single impulse constituting the first party digit, it completes a circuit at the inner armature through the first-position 75

contacts of wiper 1532 for code-group switching relay 1515. Relay 1515 thereupon operates and closes a locking circuit for itself at its inner upper armature, while at its upper armature it disconnects the ringing lead from the contacts associated with wiper 1531 and transfers it to the contacts associated with the two-digit-code wiper 1532. In addition, relay 1515 at its lower contacts opens a point in the circuit of relay 1508 so as to prevent this relay from operating through off-normal contacts 1534 responsive to the restoration of series-auxiliary relay 1550, following the restoration of relay 1509.

Under the present assumption, the next digit dialled is one having any desired value from 1 to 5 and therefore containing from one to five impulses. Wipers 1531 and 1532 are accordingly advanced until wiper 1532 bridges the desired one of the contact sets associated with the coded generator leads 1533.

With code-group relay 1515 operated and locked to conductor 1418, the lower armature of rotary-series relay 1550 is now grounded. When relay 1510 is now reoperated upon the dialling of the final party digit, their ground potential is extended to the winding of sequence relay 1514. Relay 1514 locks itself to conductor 1418 at its upper armature, while at its lower armature it prepares a circuit for operating relay 1508 which becomes closed upon the restoration of series-auxiliary relay 1510.

The ringing circuit is completed upon the actuation of pick-up relay 1512 responsive to being connected up to lead 1523 by relay 1508. This ringing circuit extends from any one of the two-digit, coded-generator leads 1533, through the contact pair bridged by wiper 1532, contacts of the operated code group relay 1515, and thence as previously traced, through the winding of ring-cut-off relay 1507, to the called line, by way of the negative wiper 1500.

When the called subscriber responds, ring-cut-off relay 1507 operates and locks itself to conductor 1418; removes ground from interrupter 1524; and at its two uppermost armatures it opens the ringing circuit and completes the talking circuit. At this point, back bridge relay 1506 operates over the called line and brings about the operation of back-release relay 1505 to prepare a circuit for recall relay 1501.

Clearing out the established connection

When the ensuing conversation has been terminated and the called subscriber replaces his receiver, the restoration of back-bridge relay 1506 results in the transmission of an impulse to recall relay 1501 for the length of time required for the slow-releasing, back, release relay 1505 to restore. Recall relay 1501 grounds the upper talking conductor 1416 so as to hold line relay 1502 operated, and it projects ringing current back over conductor 1417 to the Genesee exchange for the purpose of operating a ring-off signal in the toll cord circuit.

It will be understood, of course, that recall relay 1501 is operated in this manner when the calling subscriber merely actuates his hook momentarily for the purpose of recalling the operator.

When relay 1501 restores, it terminates the application of ringing current and again places line relay 1502 under the control of the toll line TL2.

When the operator takes down the connection at the jack J2, the resulting opening of the bridge

across the toll line TL2 results in the restoration of line relay 1502. An impulse is transmitted at this time to rotary series relay 1509, and auxiliary relay 1510 is operated, but their momentary operation at this time is only incidental. It is to be noted that busy relay 1508, having been operated as previously explained through off-normal contacts 1535, maintains the circuit of operating magnet 1533 open.

When release relay 1703 restores and removes ground potential at its upper contacts from conductor 1418, relays 1515, 1514, 1511, and 1507 are permitted to restore. Release magnet 1530 operates through off-normal contacts 1526 to restore the wiper 1500 to their normal position, and release magnet 1534 operates through contacts of busy relay 1408 to restore the party selector PS2 to its normal position. Relay 1508 releases when off-normal contacts 1535 are opened, upon the restoration of wipers 1531 and 1532 to normal position.

Signalling over four-party lines

At this point it may be mentioned that negative-generator relay 1513, positive-generator relay 1516, line-reversing relay 1517, and the negative and positive generator leads 1519 and 1518 are provided at the toll connector TC2 for the same purpose as the previously described negative-generator relay 712, positive-generator 714, line-reversing relay 715, and the negative and positive generator leads 734 and 733, of the local connector LOC. Since the operation of the local connector LOC in the signalling of full-selective party-line stations by the use of negative and positive, superimposed ringing current has been described in connection with connector LOC, such description with reference to the toll connector TC2 is omitted.

Reverting calls

The way in which the apparatus at the Leicester exchange operates in order to permit the called substation to be signalled when the called substation is on the calling line will now be pointed out.

Each of the party-line subscribers is assumed to be informed as to which other subscribers are served over his line. It is assumed further, that a subscriber wishing to call someone else on his own line, in addition to informing the operator the desired number, informs her that the desired substation is on the calling line. The calling subscriber then replaces his receiver to permit the ringing operation to take place. Relays 706 and 707 restore, but the connection is held by the ground potential normally supplied to conductor 623 through contacts of relays 702, 702', and 708.

In this case, the operator omits the tens and units digits in the requested number and dials the reverting-call digits 7 and 0 in lieu thereof. In the local connector LOC, Fig. 7, the dialling of the reverting-call digits 7 and 0 results in the shifting of the springs 722 and 762 to alternate position.

When the switch wipers 700 reach their No. 70 position, the C wiper 700 does not encounter an idle-indicating potential on the engaged bank contact, as the bank wires have been removed from the No. 70 contacts to avoid interference between connectors in the reverting-call position. However, the No. 70 contact 762 is closed at this time, and to apply a negative potential through the resistor 763 to the C wiper for the purpose of completing a circuit through contacts of connecting relay 703 and over test conductor 960 for 75

- operating idle-test relay 921, assuming that the common-equipment unit CE1 is the one in use. At the same time, the No. 70 contacts being actuated to alternate position, complete a circuit for the lower winding of switch-through relay 705 through contacts of busy relay 704 and contacts of ring-cut-off relay 710 to the grounded conductor 734. Switch-through relay 705 now operates to disconnect the incoming conductors 621 and 622 from the portion of the talking circuit extending between line and back-bridge relays 706 and 709 by way of talking condensers 729 and 730, and it extends them to the negative and positive wipers 700, for the purpose of permitting the 15 ringing current normally transmitted from wiper 700 through the bank multiple to pass back over the incoming conductors 621 and 622 to the calling line. At its inner lower contacts, switch-through relay 705 closes a circuit for release relay 20 707 so as to reoperate this relay and prepare a new holding circuit which is necessary to maintain the holding conductor 623 grounded after cut-through relay 702 is operated upon the clearing out by the control operator.
- 25 The operator following the dialling of the reverting-call digits 7 and 0 by the dialling of the requested party designation, thereby causing the party selector PSI to be set in a position to cause the designated substation to be signalled.
- 30 When the operator clears out, cut-off relay 702 operates over the cut-off conductor 955 and connects up the pick-up and interrupter-start conductors 735 and 736 so as to start the ringing interrupter and to operate pick-up relay 711 to 35 start the ringing operation. The ringing operation now results in ringing current being transmitted back through contacts of the operated switch-through relay 705 to the calling line.
- When the calling subscriber again removes his receiver or the called subscriber answers, whichever occurs first, ring-cut-off relay 710 is operated in the ringing circuit. Upon operating, in addition to closing its locking circuit at its inner lower contacts and opening the ringing circuit, ring-cut-off relay 710 at its middle lower armature opens the circuit through the lower winding of switch-through relay 705, causing switch-through relay 705 to restore and reconnect line relay 706 to the incoming conductors 621 and 622.
- 45 Line relay 706 is now reoperated over the calling line to close a holding circuit for release relay 707 and maintain it operated so as to maintain ground potential on holding conductor 623 until the end of the conversation.
- 50 The connection clears out in the manner hereinbefore explained when both subscribers replace their receivers and permit the line relay 706 to restore.
- 55 What is claimed is:
- 60 1. In a telephone system wherein automatic switches used for completing local connections between lines of the same exchange are controlled from a remotely located exchange, a pair of operating trunks over which the control is effected, 65 two common-equipment units each terminating a corresponding operating trunk, two stepping magnets in each of said switches for variably positioning said switches, two control conductors corresponding respectively to said stepping magnets extending from each common-equipment unit, means for interconnecting the control conductors of either common-equipment unit with the stepping magnets of any of said switches, and means for delivering a series of impulses over 70 each connected control conductor to the magnet

to which it is connected to thereby effect a desired positioning of the switch.

2. In a telephone system wherein automatic switches used for completing local connections between lines of the same exchange are controlled from a remotely located exchange, a pair of operating trunks over which the control is effected, two common-equipment units each terminating a corresponding operating trunk, a separate group of control conductors extending from each of said units to said switches, means for taking any one of said switches for use and for thereupon associating either of said units therewith through the group of control conductors of such unit, and means in the associated unit controlled over the corresponding operating trunk for controlling the setting of said switch over the control conductors.

3. In a switching system, a group of switches, common-equipment units associated with said group of switches, two groups of relay contacts in each switch, each group actuatable to connect the switch with a separate common-equipment unit, and interlocking means for insuring that both of said sets of contacts in a switch are not actuated at the same time.

4. In a switching system, a group of switches, common-equipment units associated with said group of switches, two groups of relay contacts in each switch, each group actuatable to connect the switch with a separate common-equipment unit, interlocking means for insuring that both of said sets of contacts in the same switch do not become actuated at the same time, and means common to all the switches for insuring that corresponding contact sets in two switches do not become actuated at the same time.

5. In a telephone system wherein automatic switches used for completing local connections between lines of the same exchange are controlled from a remotely located exchange, a pair of operating trunks over which the control is effected, two common-equipment units each terminating a corresponding operating trunk, means for taking said switches for use separately, means for allotting an idle one of said common-equipment units to the exclusive use of a switch when the switch is taken for use, and means for preventing a switch from being taken for use at a time when no common-equipment unit is available.

6. In a switching system, a group of finder-connector links, a control unit common to the finders of such links for controlling the positioning thereof, two control units common to the connectors for controlling the positioning thereof, means for associating said control units individually with the finders and connectors, and means effective when no control unit is available for association with a connector for preventing the finder control unit from exercising its control over the linked finder.

7. In a telephone system wherein automatic switch apparatus used for completing local connections between lines of the same exchange is controlled from a remotely located exchange, a pair of operating trunks over which the said control is effected, each of said operating trunks terminating at the remotely controlled exchange in a common-equipment unit common to a number of automatic switches, means in each common-equipment unit for directly controlling the positioning of any local automatic switch, and means effective when a call is originated in the remotely controlled exchange for interconnecting the calling line with an automatic switch and for inter-

connecting the switch with an idle one of the common-equipment units to enable the switch to be operated over the operating trunk through the common-equipment unit to complete the connection.

5. In a telephone system wherein automatic switching apparatus located in a first exchange is remotely controlled from a second exchange to interconnect local lines of the first exchange, 10 operating trunks extending from the second exchange to the first over which the remote control is effective, means normally effective responsive to the origination of calls in the remotely called exchange for taking one of said 15 operating trunks for use if at least one of them is idle and for preventing the taking for use of an operating trunk when it is already in use, means responsive to the setting of automatic switching apparatus in the remotely controlled 20 exchange to a predetermined position for removing one of said operating trunks from service, and other means responsive to the setting of switching apparatus in the remotely controlled exchange in a different position for removing the 25 other operating trunk from service.

6. In a telephone system wherein automatic switching apparatus located in a first exchange is remotely controlled from a second exchange to interconnect local lines of the first exchange, 30 operating trunks extending from the second exchange to the first over which the remote control is effective, means normally effective responsive to the origination of calls in the remotely called exchange for taking one of said 35 operating trunks for use if at least one of them is idle and for preventing the taking for use of an operating trunk when it is already in use, means responsive to the setting of automatic switching apparatus in the remotely controlled 40 exchange to a predetermined position for removing one of said operating trunks from service, other means responsive to the setting of switching apparatus in the remotely controlled exchange in a different position for removing the 45 other operating trunk from service, and additional means responsive to the setting of the switching apparatus in the remotely controlled exchange in pre-assigned other positions for returning the operating trunks respectively to 50 service.

7. In a telephone system, a remotely controlled semi-automatic exchange, operating-trunk terminating equipment in the semi-automatic exchange, a first operating trunk extending to an 55 operating point by way of a given route, a second operating trunk extending to an operating point by way of a different route, and means in the remotely controlled exchange for connecting the same operating-trunk terminating equipment 60 with either of said operating trunks, whereby when one operating trunk becomes unserviceable because of bad line conditions the alternative operating trunk, extending along a different 65 route, may be substituted.

8. In a telephone system, a remotely controlled semi-automatic exchange, a second exchange lying in a given direction from the remotely controlled exchange, a third exchange 70 lying in a different direction from the remotely controlled exchange, trunk lines extending from the first exchange to the second exchange, other trunk lines extending from the remotely controlled exchange to the third exchange, one of 75 the trunk lines extending from the remotely con-

trolled exchange to the second exchange being normally connected to operating-trunk terminating equipment in the remotely controlled exchange and normally used as an operating trunk, and means in the remotely controlled exchange 5 for disconnecting the operating-trunk terminating equipment from the normally connected operating trunk and for transferring it to a trunk line extending to the third exchange, whereby, in the event of general line trouble between the 10 remotely controlled exchange and the second exchange, operation of the remotely controlled exchange may be carried on over a trunk extending from the remotely controlled exchange over a different trunk route to the third exchange. 15

9. In a telephone system, a remotely controlled semi-automatic exchange, two operating trunks extending to said exchange and normally connected with operating-trunk terminating equipment therein to facilitate handling of calls 20 originated in the remotely controlled exchange, remotely controlled means in the remotely controlled exchange for removing either operating trunk from service when it becomes defective, so as to thereby cause all calls originated in the 25 remotely controlled exchange to be handled over the remaining operated trunk, and remotely controlled means located in the remotely controlled exchange for transferring one operating-trunk terminating equipment to a third line to enable 30 this third trunk line to be used as an operating trunk and for removing the other operating-trunk terminating equipment from service, whereby in the event that both of the normally employed operating trunks become defective the 35 third-named trunk may be used as an operating trunk to effect operation of the remotely controlled exchange through one operating-trunk terminating equipment, while calls are prevented from going to the remaining operating-trunk 40 terminating equipment.

10. In a common-battery telephone system employing a switchboard operator, means for setting up a connection from a calling line to the switchboard and for signalling the switchboard operator responsive to the current flow which takes place upon the removal of the receiver on the calling line, a separate lock-out apparatus individual to each subscriber line, and means controlled from the switchboard for breaking down 50 a connection extending thereto and for operating the said lock-out apparatus of the calling line to prevent a re-extension of a connection to the switchboard while current continues to flow over the calling line, whereby, when the operator is signalled responsive to a current flow occasioned by a line defect or by the accidental closure of the hookswitch contacts, the offending line may be locked out of normal service. 55

11. In a common-battery telephone system employing a switchboard operator, a separate lock-out device individual to each of certain of the subscriber lines, means responsive to the current flow which takes place when the receiver is removed on a calling line for signalling the switchboard operator, and means controlled from the switchboard for actuating the lock-out device individual to the subscriber line over which the operator is signalled, and means included in said 60 lock-out device for maintaining the device operated responsive to current flow over the subscriber line, whereby, when a line becomes defective sufficiently to cause the operator to be signalled spontaneously, the lock-out device may be 65 70 75

- operated to bar the subscriber line from signalling the operator until the defective condition is terminated.
15. In a common-battery semi-automatic telephone system, means responsive to the removal of the receiver on a calling line for connecting such line with call-extension equipment and for setting up a branch connection to the equipment, means under the control of the operator for 5 extending connection from the calling line to a called line and for breaking down the branch connection to the control equipment, either after extension of the connection or without extending the connection, and means responsive to the 10 breaking down of the branch connection without an extension of the connection to a called line for locking the calling line out of service, whereby, when a call is falsely initiated responsive to a fault on the line, the faulty line is locked out of 15 service and the faulty condition is prevented from interfering with the giving of service to other lines.
16. In a common-battery-signalling semi-automatic telephone system, means responsive to current flow over a calling line when the receiver 20 is removed for inter-linking the calling line with call-extending apparatus and for setting up a branch connection to the operator's switchboard, means controlled from the operator's switch- 25 board for extending connection from the calling line to a desired called line and for breaking down the branch connection either after the completion of the extension or before the extension is completed, and means automatically responsive to the breaking down of the branch connection 30 before the extended connection is completely set up to a called line for removing the calling line from service and for holding it removed from service dependent upon the continuation of current flow thereover, whereby the common equipment is returned to common use automatically 35 without waiting for the calling subscriber to replace his receiver and thereby clear out a partially established connection.
- 40 17. In a telephone system wherein connections from calling lines to called lines are set up by way of link circuits under the control of a switchboard operator, means operated incidental to the setting up of a connection for testing the desired line, means effective when the desired line is in use and including test equipment common to all 45 said links for applying busy-signalling current to the calling line in the event that the called line is busy, means for disconnecting the common equipment from the link, and for continuing the application of busy-signalling current from the link after the common equipment has become disconnected.
- 50 18. In a telephone system, a group of links, switching apparatus operable to interconnect calling and called lines by way of said links, a common-equipment unit common to all of said links, means for temporarily associating said common-equipment unit with one of said links when a 55 call is to be extended thereover, means included in the common-equipment unit for testing the called line, means in the common-equipment unit effective in the event that the called line is busy 60 for applying busy-signalling current by way of said link to the calling line, means for subsequently terminating the temporary association between the link and the common-equipment unit, and means thereupon effective and dependent upon the called line having tested busy for 65
- continuing the application of busy-signalling current to the calling line from the link.
19. In a telephone system, party lines equipped for party signalling to be carried out according to one ringing system, other party lines equipped for party signalling to be carried out according to a different ringing system, an automatic switch having access to all of said party lines, means for operating said automatic switch to make connection with any desired one of said party lines, 10 party-selecting apparatus associated with said automatic switch, and means for actuating said party-selecting apparatus to prepare for the signalling of the desired station on the called party line according to the ringing system for which 15 the line is equipped.
20. In a telephone system, two groups of party lines, a group of common ringing leads provided for signalling the party lines of the first group, a group of common ringing leads provided for the 20 signalling of party lines in the second group, a connector switch having access to all of said party lines, means for operating said switch to make connection with a desired one of said party lines, auxiliary party-selecting apparatus associated with said switch, and means for operating said party-selecting apparatus to select the desired party on a called party line and to thereby associate one of said ringing leads of the corresponding group with said connector switch for 25 the signalling of the desired substation on the called party line.
21. In a telephone system, a group of code-ringing party lines, a group of selective-ringing party lines, an automatic switch having access to 30 all of said lines, party-selecting apparatus individual to said switch, means for operating said switch to make connection with a desired party line, means for operating the said party-selecting apparatus to prepare for signalling the desired station on the called party line, and means controlled according to the setting of the party selecting apparatus for causing the desired substation to be signalled in code in the event that the called line is a code-ringing line and to be signalled selectively in the event that the called line 35 is a selective-ringing line.
22. In a telephone system wherein connections to called party lines are set up through automatic switches, a party selector individual to an automatic switch and comprising a switch structure having a plurality of selectable bank contacts, a positive-biased and a negative biased generator lead associated with certain contacts of said party selector, coded generator leads connected to other of said bank contacts, and means for setting said party selector preparatory to a ringing operation onto any one of said contacts to secure the transmission of ringing current from the desired one of said leads over a called party 40 line.
23. In a telephone system wherein connections to called lines are set up through automatic switches, an automatic switch having party-selecting apparatus associated therewith, said party-selecting apparatus including a variably actuatable switch and a plurality of bank contacts, coded generator leads associated with certain of said contacts, generator-connecting relays associated with others of said contacts, and a line-reversing relay associated with the last-named contacts and variably operable with said generator-connecting relays.
24. In a telephone system wherein connections are set up through a group of automatic switches, 45

- a common-equipment unit associated with a group of automatic switches, means for temporarily connecting said common-equipment unit to one of said automatic switches to the exclusion of all the others, means for transmitting the digits of any desired telephone number to said unit, the number of digits being variable, means in said unit effective in each case for transmitting the required number of digits to the connected automatic switch, and means in said unit effective when the required number of digits has been transmitted and depending upon the telephone number being called for disabling the unit from transmitting any more digits to the automatic switch, whereby the setting of the automatic switch is not disturbed in the event that additional digits are transmitted to the common-equipment unit.
25. In a telephone system wherein connections are set up to called lines by way of automatic switches, an automatic switch having access to a group of lines having a common call number assigned thereto, said switch being responsive to impulses representing the call number to advance its wipers into association with the first line of the group, means associated with said switch for testing the line and for indicating whether the line is busy or idle, means responsive to further directive impulses received by said switch when the line first engaged is busy for advancing it successively into engagement with succeeding lines of the group, and means controlled by the said testing means for disabling the switch from responding to further directive impulses when connection is made with an idle line of the group.
26. In a telephone system, a connector having access to party lines, each party-line subscriber number including digits required to operate the connector to make engagement with a desired line and additional digit information indicative of the desired station on the party line, party-selecting apparatus responsive to the said additional digit information, when dialled, said connector being responsive following the dialling of the party-digit information in the event that the called line is busy for advancing to a succeeding line, the arrangement being such that an indefinite number of succeeding lines may be successively contacted and tested, and means effective when a line is found to be idle for disabling the connector from responding to further digit impulses, whereby when a number of lines have a common call number the connector may be directed into successive engagement with the lines until all have been tested or until one of them is found to be idle.
27. The method of controlling the operation of a connector switch and associated party-selection apparatus in the selection of an idle line of a group which consists in first positioning the connector on the first line of a group, in then positioning the party-selecting apparatus in accordance with an assigned party digit, in then successively positioning the connector on succeeding lines of the group until all have been tested or until one of them is found to be idle, and in disabling the connector from further advance responsive to the encountering of an idle line in the group.
28. In a telephone system wherein automatic switching apparatus is remotely operated to effect the setting up of local connections by way of local links, a pair of operating trunks and associated terminating equipment, means controlled over a calling line for connecting the calling line with an idle local link and for thereupon connecting the local link with an idle one of said operating trunks and associated terminating equipment, means normally operable over the connected operating trunk for actuating automatic switching apparatus to complete the connection and to thereafter break down the connection between the local link and the operating trunk and associated terminating equipment, means effective after the local link has become connected with the idle operating trunk and associated terminating equipment for maintaining the calling line connected with the local link and for maintaining the local link connected with the operating-trunk terminating equipment until the connection has been extended, means effective when desired for removing either of said operating trunks from service and thereby preventing the extension of any more connections thereto from local links, and means thereupon effective in the event that a local link is currently connected to the terminating equipment of the operating trunk for severing the connection between the local link and the operating-trunk terminating equipment and for severing the connection between the calling line and the local link.
29. In a telephone system wherein the switching apparatus in a remotely controlled exchange is positioned to set up connections originated on lines of the remotely controlled exchange responsive to control impulses transmitted thereto from the switchboard of a control operator over an operating trunk, means responsive to a call being originated on a line of the remotely controlled exchange for taking a local switch for use and for connecting such local switch with the operating trunk, means for thereupon signalling the control operator to make connection with the control trunk pursuant to the controlling of the setting up of the desired connection by way of said switch, means effective when the line called is another local line for starting the transmission of ringing current to the called line responsive to the control operator disconnecting her equipment from the control trunk, a given position of the local switch being set aside for the handling of long distance calls, and means effective when the number called is one which causes the local switch to be set in long-distance position for causing a connection to be completed over a long-distance line while the control operator is still connected with the control trunk, whereby the control operator may converse over the long-distance line before she disconnects her equipment from the control trunk.
30. In a telephone system wherein automatic switching apparatus located in a telephone exchange is controlled from a remote operating point over an operating trunk to complete calls originated in the remotely controlled exchange, means responsive to the origination of a call on a line local of the remotely controlled exchange for signalling an operator at the operating point over an operating trunk, a timing device and means for starting it into operation when the signalling is accomplished, and means controlled by said timing device and dependent upon the call being unanswered upon the expiration of the predetermined length of time for sounding a local alarm.
31. In a telephone system wherein automatic switching apparatus in a remotely located exchange is controlled from a distant point, there being a pair of operating trunks provided over

either of which the switching apparatus in the remotely controlled exchange may be controlled, means effective when a call is initiated in the remotely controlled exchange for taking an idle 5 one of said operating trunks for use, local operating equipment provided in the remotely controlled exchange, and means for enabling an operator at the remotely controlled exchange to intercept all calls directed to one of the operating 10 trunks and control the local switching apparatus thereover, while permitting calls direct to the other operating trunks to pass thereover and be handled from the operating point.

32. In a telephone system wherein automatic switching apparatus in an exchange is normally remotely controlled from a remote operating point, a pair of operating trunks extending from the remotely controlled exchange to the operating point, means in the remotely controlled exchange responsive to a call being originated on one of the local lines for taking an idle one of the operating trunks for use to enable the necessary automatic switching apparatus to be controlled thereover to extend the calling line, local operating equipment, and means for causing all calls directed to one of the operating trunks to be in-

tercepted at the local operating equipment and for preventing any further calls from being directed to the other operating trunk, whereby a local operator at the remotely controlled exchange may take over the complete operation 5 of the exchange when it becomes necessary.

33. In a telephone system, lines of a given class, trunks leading to a manual switchboard used for handling calls from lines of said given class and for handling calls from lines of another 10 class, means responsive to the origination of a call on a line of said given class for extending the calling line to an idle one of said trunks, a timing device associated with the calling line, means controlled by said timing device for giving 15 an alarm in the event that the calling line is not connected with an idle trunk to within a predetermined time following the origination of the call, means for signalling the operator over a trunk when connection is made thereto, and 20 means responsive to the answering of the call at the manual switchboard and controlled by said timer for applying a tone signal impulse indicative of said given class, whereby the operator is informed as to the class of the calling line. 25

EDWARD S. PETERSON.
